UNITED STATES PATENT OFFICE

2,039,338

VACUUM CLOSING MACHINE

Ronald E. J. Nordquist and John Daniel Le Frank, Maplewood, N. J., assignors to American Can Company, New York, N. Y., a corporation of New Jersey

Application July 30, 1932, Serial No. 627,084

47 Claims. (Cl. 113—1)

The present invention relates to a machine or apparatus for sealing or closing containers under vacuum, the containers and container covers being rapidly conveyed into a vacuum chamber and presented to sealing mechanism positioned within the chamber where they are hermetically sealed, after which the sealed containers are removed from the chamber, all of such operations being performed by the use of valve members without materially changing the vacuum within the chamber.

An important object of the present invention is the provision of an apparatus for vacuum sealing containers in an enclosed vacuum chamber associated with non-floating can carrier valves for conveying the containers or cans into and discharging them from the vacuum chamber by passage through flexible float valve members interposed between the carrier valves and the casing of the vacuum chamber.

An important object of the invention is the provision of an apparatus of the character described in which vacuum of a predetermined value may be maintained in a vacuum chamber and in which the sealing of the container within the chamber is automatically and electrically prevented unless there is this proper predetermined vacuum.

A further important object of the invention is the provision of electrical stop devices for controlling the operations of the machine and for preventing improper sealing of containers by stopping the machine when abnormal conditions exist in any one of a number of stations, these electrical stops having common terminal points of inspection so that determination of the trouble may be quickly and easily made.

A further and important object of the invention is the provision of an electrical stop device, which operates to prevent passage of containers into the sealing chamber when the supply of can covers falls below a predetermined quantity.

An important object of the invention is the provision of a manual control for starting and stopping an electric motor which is used as the prime power mover, such control permitting starting of the motor only when there is no load on its drive shaft and insuring proper speed of rotation for the motor before the load of the machine can be transferred to it.

A still further important object of the invention is the provision of a common drain for spilled liquids or other foreign matter within the vacuum chamber, this drain being automatically

emptied periodically without breaking or affecting the vacuum within the vacuum chamber.

An important object of the invention is the provision of cleaning and lubricating devices for the rotating valve members of the apparatus which insure uninterrupted ease of operation with maximum sealing of the vacuum chamber by the valves.

A still further object of the invention is the provision of adjusting devices in an apparatus of the character described which permit accurate and ready adjustment of the travel of a can cover from the magazine, through the marking devices and into can assembling position.

Numerous other objects of the invention will be apparent as it is better understood from the following description, which, taken in connection with the accompanying drawings, discloses a preferred embodiment thereof.

Referring to the drawings:—

Figure 1 is a front elevation of a preferred form of apparatus embodying the present invention;

Figs. 2, 3, 4 and 5 are enlarged sectional views which collectively disclose one longitudinal sectional plane of the apparatus, Figs. 2 and 3 showing, respectively, the upper and lower parts of the left end of the machine and Figs. 4 and 5 showing the right end of the apparatus, these latter views joining each other side by side with Fig. 3 to complete the section;

Figs. 6, 7 and 8 are enlarged plan sectional views taken at different levels and indicated respectively as sections taken substantially along the broken lines 6—6, 7—7 and 8—8 in Fig. 1;

Fig. 9 is a top plan view of the left end of the apparatus being practically a plan view of Fig. 2;

Fig. 10 is a combination side elevation and sectional view of the parts illustrated in Fig. 9 being taken substantially along the broken line 10—10 in that figure;

Fig. 11 is a transverse sectional detail taken substantially along the line 11—11 in Fig. 10;

Figs. 28, 29, 30 and 31 are sectional details on an enlarged scale of the cover magazine being fragmentary sections similar to Fig. 22, the different views illustrating different positions of a cover during its removal from the magazine;

Fig. 32 is a plan sectional view taken substantially along the broken line 32-32 in Fig. 22;

Fig. 33 is a sectional detail taken substantially along the line 33-33 in Fig. 28;

Fig. 34 is an under plan view of the parts illustrated in Fig. 33, as viewed from a position indicated by the line 34-34 in that figure;

Figs. 35 and 36 are fragmentary sectional details, respectively, of two steps in the feeding of a cover being sections substantially along the line 35-35 in Fig. 32;

Fig. 37 is a transverse sectional detail taken substantially along the line 37-37 in Fig. 35;

Fig. 38 is an enlarged sectional view taken substantially along the broken line 38-38 in Fig. 6;

Fig. 39 is a plan sectional view taken substantially along the line 39-39 in Fig. 38;

Fig. 40 is an enlarged front elevation, partly in section, of the exit valve as viewed substantially along the line 40-40 in Fig. 6;

Fig. 41 is an enlarged transverse sectional schematic view, showing in spread out positions with parts swung around into a single plane, the parts traversed by the broken sectional lines 41-41 in Fig. 8;

Fig. 42 is a transverse sectional detail taken substantially along the line 42-42 in Fig. 41;

Fig. 43 is a plan sectional detail taken substantially along the line 43-43 in Fig. 3;

Fig. 44 is a plan sectional detail taken substantially along the line 44-44 in Fig. 2;

Fig. 45 is plan sectional detail taken substantially along the line 45-45 in Fig. 4;

Fig. 46 is an enlarged fragmentary sectional view taken substantially along the line 46-46 in Fig. 7; and

Fig. 47 is a wiring diagram of the electrical stop control units of the apparatus.

The apparatus, illustrated in the drawings as a preferred embodiment of the invention, comprises a fully automatic machine in which filled open top cans are introduced in untimed order

from a suitable source of supply, are registered in proper time with the operations of the apparatus without spilling (if there are liquid contents in the cans) and are further transferred from the timing mechanism into a pocket of an entrance valve which carries the cans into a vacuumized chamber. Can covers are also automatically fed from a stack of covers in a magazine, a single cover being separated from the magazine only when a can is brought into the machine. This separated cover is conveyed through a marking station where it pauses long enough to receive a mark or imprint and is then brought into the valve pocket which immediately afterwards receives the can as described.

The can and cover while in the valve pocket and after they leave the pocket and enter into the vacuum chamber are maintained in axial alignment but are held separated from one another to avoid any restriction to the removal of air from the can. A transfer turret operating within the chamber receives the can and cover from the valve and positions the can in a seaming turret and upon one of four plunger units carried in a seaming turret and associated with seaming heads, the cover being deposited upon the can at such time. The seaming heads are continuously carried in a circular path of travel within the chamber by the seaming turret.

At this time the air has been exhausted from the interior of the can and the cycle of vacuumization has been completed. It will be recalled that this cycle began with the progressive withdrawal of air when can and cover were still in the entrance valve pocket. The plunger unit lifts the assembled can and cover clamping them together and between the plunger and the chuck of the seaming head. The seaming operation which follows secures the cover flange to the body flange in a double seam after which the fully seamed can leaves the seaming turret and is transferred by a starwheel into a pocket of an exit valve. This valve conveys the can to the outside of the vacuum chamber and places it into a discharge starwheel which removes it from the machine.

The preceding brief statement of operation is only in barest outline and makes no mention of many associated features connected with the operation of seaming of a can and cover in vacuum within the machine. The most important of these auxiliary elements will now be briefly considered after which a fully detailed description will be given.

The vacuum chamber is maintained at a predetermined degree of vacuum, the air being constantly removed as turret pockets of air are brought into the chamber by way of the entrance and exit can conveying valves and as air enters with the filled cans. An automatic control device is associated with the vacuum line connected to the chamber. In the event that the effective degree of vacuum within the chamber falls below the predetermined point a combination sylphon and electrical stop device operates to stop the machine.

All of the moving parts of the various units of the machine are driven by connection with a main shaft which is continuously rotated during the normal operation of the machine by connection with an electric motor. This electric motor is electrically associated in series with a plurality of electrical stop devices which prevent starting of the motor or which stop the operation of the motor if already running, when ab-

normal conditions arise at any one of several locations throughout the machine. The circuits for these different electrical stops all come into a single terminal box where a simple inspection 5 easily locates any trouble.

The driving connection from the motor to the main shaft is made through a friction clutch which is mechanical in its operation and one of its uses is to allow manual control of the starting 10 and stopping of the apparatus. Provision is made for preventing the starting of the motor if the clutch is in position to establish driving connection between the main and motor shafts. This feature prevents the motor picking up a 15 load when starting from a dead stop and the load of operation of the machine can only be picked up after the motor has attained its speed.

The vacuum chamber is provided with a floor which slopes to one common drain pipe which 20 connects with a rotary drain valve. From this valve accumulated liquid is automatically discharged to the atmosphere without breaking the vacuum. This liquid may be fruit juices, brine or other liquid which may spill or slop from the 25 cans being seamed in the chamber either during normal operations or during a jamming or improper feeding of the cans.

Provision is also made for automatically cleaning and lubricating the entrance and exit valve 30 wearing surfaces so that the highest degree of air-tight joint may be maintained at these places. This is done by a discharge of water on the surfaces and this first dissolves any syrup or fruit 35 juices which may be present and then a discharge of glycerine or oil lubricates the valve surfaces.

A close cooperation is maintained between the can cover magazine, the cover feeding devices and the cover marking unit and these are mounted 40 for ready and accurate adjustment to the height of can being vacuumized and seamed. This feature insures accuracy of can and cover assembly.

General frame structure

The machine illustrated in the drawings, comprises broadly a stationary part enclosing a vacuum chamber and two hinged can conveying valve units. These valve units, entrance and 50 exit, are severally pivotally connected with the stationary parts of the machine and while each valve unit continually rotates in one position, the entire valve unit and certain other mechanism connected with it may be swung outwardly 55 away from its seat so that ready access may be had to the interior of the vacuum chamber.

The swinging frame of the entrance valve unit not only carries the valve and its associated parts but also the magazine for can covers, the marking devices for the covers and the timing device 60 for placing the can into proper synchronism with the operating parts of the machine. In a similar way the exit valve unit frame also carries the discharge starwheel and certain other associated parts. The general stationary frame features of the machine will first be considered in connection with the vacuum chamber and the construction 65 of the housings, casings and associated parts which enclose it.

This stationary structure comprises a base 51 (Figs. 1, 3 and 8) which extends substantially under the entire machine and which carries a lower casing 52. The base 51 is preferably formed with an upstanding peripheral rim 53 which 75 surrounds a substantially horizontal central section

54. This area within the rim forms a collecting basin for oil, juices, brines, etc. which are prevented from falling on the floor. An intermediate frame ring section 57 is carried upon the lower casing 52 and engages with a flange 58 which 5 projects outwardly from the wall of the casing, this ring section being larger than the body of the casing (see also Fig. 7).

The section 57 in turn supports a main vacuum chamber housing 61 (Figs. 1, 2, 3 and 4). A cover 10 member 62 is bolted to the chamber housing and provides an air-tight top closure for the vacuum chamber, the central part of the cover being formed with an opening 64 to permit assembly of certain of the working parts of the apparatus. 15 A cap 65 is secured by bolts to the cover and closes the opening 64 in an air-tight joint. The housing 61 with its covers 62, 65 and the ring section 57 provide an enclosing shell for the vacuum chamber, designated by the numeral 71. 20

The wall of the housing 61 is cut through at several places to provide openings for easy access to the interior of the chamber and for assembly purposes and the frame section 57 has one opening for a like purpose. The largest of the openings in the housing 61 is designated by the numeral 75 and is illustrated in Figs. 2, 3 and 6. A door 76 is provided for closing this opening being tightly shut and clamped in closing position during the normal operation of the machine. 25 The housing wall outside of and surrounding the opening is formed as a smooth and flush surface 77 against which a continuous door gasket 78 is adapted to engage. This gasket is contained within a continuous groove 79 formed in the door 30 76. The door along one side is projected outwardly in lugs 81 which are pivotally mounted on pins 82 carried in lugs 83 formed in the wall of the chamber housing. This construction provides a hinging action for the door. 35

Similar lugs 85 are formed along the opposite side of the door and are slotted at 86. After the door is closed it is tightly clamped with the gasket 78 pressed in an air-tight joint against the housing surface 77. The unhinged side of the door 40 45 is so held by clamping bolts 87 which are pivoted at 88 on lugs 89 projecting outwardly from the wall of the chamber housing and these bolts are swung into the slots 86 and threaded engaged by hand nuts 91. On the hinged side a similar 50 clamping action is obtained by clamping bolts 92 pivoted on the pins 82 and loosely extending through the lugs 81 where they are threaded engaged by other hand nuts 93.

The door 76 is preferably provided with a window being cut through in an opening 97 in which is tightly secured a glass or other suitable transparent member 98 held in place by a ring 99. The position of this window makes it possible to inspect the can and seaming mechanism during 60 the seaming operation.

A second opening 105 (Figs. 1 and 6) may also be formed in the chamber housing 61 and may be closed in a similar manner by a door 106. This opening and door are less in height than the opening 75, 76 just described. The door is formed with lugs 107 which are pivoted at 108 to lugs 109 formed on the housing wall. Clamping bolts 111, 112 receive hand nuts 113, 114 which tightly hold the door in position, the latter 70 also swinging in a slot 115 formed in a lug 116 on the door. In the same manner a third opening 117 (Fig. 6) formed in the chamber housing may be similarly closed by a hinged, gasket lined door 118 hinged at 119 and held in clamped position 75

by suitable clamping bolts and hand nuts as shown.

The opening in the intermediate ring section 51 (Figs. 3 and 7) is tightly closed in the same 5 manner by a door 122 hinged at 123 and held in clamped position by clamping bolts 124, 125 receiving suitable hand nuts 126, 127. Such a door also carries a gasket (as at 128) the interior of the section 51 being vacuumized.

10 In addition to the three openings in the chamber housing and the opening in the ring section just described the housing surrounding the vacuum chamber is further provided with two openings 131, 132 (Fig. 6) through which respectively 15 the can and cover may enter and through which opening 131 the seamed can may be discharged after the seaming operations have been completed. These openings while providing for the desired 20 can passage are maintained closed against the entrance of air into the vacuum chamber 11. Rotating entrance and exit valves are used as can carriers and are associated with sealing float valves or valve seats for this purpose. These will be fully explained hereinafter.

25 *Motor drive and safety actuation*

All of the operating parts of the machine are preferably motor driven and a consideration will first be had of the motor and its driving connections through a mechanical slip clutch and as far as a main shaft. The chamber cover 62 supports an electric motor 141 (Figs. 1, 2 and 9).

For this purpose a baseplate 142 is mounted upon and secured by bolts 143 to the cover 62. 35 This baseplate is recessed to clear the cap 65 and it provides a support for feet 144 of the motor, bolts 145 holding the motor in secure position. A motor shaft 146 extends toward the rear and carries a sprocket 147 over which operates a chain 40 148 which also passes over a sprocket 149 (see also Fig. 10) associated with a mechanical friction clutch 151.

The sprocket 149 is pinned at 152 to an outer shell 153 of the clutch. This shell is rotatably 45 mounted upon roller bearing units 154. The inner part of each bearing unit is mounted directly upon a horizontal power shaft 155 and these bearing parts are clamped against longitudinal movement between a shoulder 156 formed 50 on the shaft and a nut 157 threadedly secured to the shaft. Longitudinal slots 158 are cut in the shaft at diametrically opposed positions (see also Fig. 11) and a pair of sliding keys 159 is located in the inner ends of the opposed slots and a pair 55 of similar keys 161 is similarly located in the outer end of the slots.

The shell 153 carries an inner sliding disc 162 which is adapted to cooperate with clutch disc plates 163 associated with an outer cup member 60 164 feathered at 165 to the outer end of the shaft 155. This member 164 is formed with a hub 166 over which a spring 167 is positioned. This spring 65 is confined between a wall of the cup member and a nut 168 threadedly engaged on the outer extremity of the power shaft.

Parts of the friction clutch 151 have slight longitudinal movement on the shaft 155 and when in one position effect engagement of the clutch. Disengagement of the clutch elements is made 70 by a reverse longitudinal movement. For this purpose the cup member 164 abuts against the ends of the outer pair of keys 161. The opposite ends of the keys 161 engage the ends of the keys 159 and heads 169 of the latter engage an 75 inner element 171 of a thrust bearing 172. These

members 164, 161, 159 and 171 are held together as a unit by the spring 167 and it is the sliding of these parts longitudinally of the shaft 155, together with the active clutch elements 162, 163, 164 that effects a clutching and unclutching of the clutch 151. This is under manual control of the operator as will be hereinafter described.

The power shaft 155 is journaled in bearings 181 (Figs. 2 and 10) which are carried in a housing cover extension 182 which rests upon and is 10 bolted at 183 to a tubular member 184 mounted upon and carried by a horizontal wall 185 which is a part of the top of the chamber housing 61 (see also Fig. 4). An extension cap 191 rests upon the upper end of the cover extension 182 and 15 these two members provide a housing for the shaft and certain gears associated with it.

The shaft 155 within this gear housing carries a bevel pinion 192 which is keyed to the shaft and is held in fixed position against the bearing 20 unit 181 by locknuts 193 threadedly connected with the shaft. This pinion 192 meshes with a bevel gear 194 carried on the upper end of a main vertical shaft 195. The main shaft 195 is indirectly journaled at its top in a pair of spaced 25 bearings 196 (Fig. 10) contained in a supporting cup 197 secured by bolts 198 to the lower end of the cover extension 182. At the bottom of the shaft 195, there is provided a pair of roller bearing units 199 (Fig. 4) which are carried by the 30 lower casing 52, these bearings indirectly supporting the shaft by means of interposed parts as will be hereinafter fully described.

Normally throughout the operation of the machine the motor 181 continually operates to rotate 35 the sprocket 149 and if the clutch 151 is in clutch position, this sprocket also rotates the power shaft 155 and the main shaft 195. All of the various working units of the machine have a driving connection directly or indirectly with 40 this main shaft which must be operating if any other operations of the machine are taking place.

Reference has already been briefly made to the safety feature of starting of the motor 141 which requires that the clutch 151 be disconnected 45 from the power shaft 155 before the motor can begin its rotation. For a more thorough consideration of this feature reference should now be had to Figs. 9 to 12 inclusive. As long as the clutch is disconnected or unclutched, the 50 action of spring 167 is nullified and the active clutch parts 153, 162, 163, 164 are held separated. This is accomplished in the following manner.

A collar 201 (Figs. 10 and 11) is slideably mounted on the shaft 155 and engages the ball 55 bearing unit 171. This collar is grooved in its outer periphery and a yoke 203 carries a pair of diametrically spaced pins 204 which engage loosely within the groove of the collar. This yoke 203 is pivoted on a vertical pin 205 (see also Fig. 6) 60 carried in a bracket formed as an integral part of the cap 191. One arm of the yoke 203 carries a swivel 206 in which a rod 207 is adjustably secured.

The rod 207 is pivotally connected at 208 to an oscillating disc 209 having movement upon a stud 211 threadedly secured in the cap 191. The disc 209 when moved into the position shown in Fig. 9 forces the yoke 203 toward the end of the 7 shaft 155 and holds the collar 201 so that the clutch 151 is disconnected. The pivot point 208 is passed the dead center between the points 206, 211 and the spring 167 acting through the 7 sliding keys, collar and yoke holds a screw 212, 1

carried in a lug 213 formed in the disc, against a stop 214 on the cap 191. Disc 209 carries a pin 216 on which is pivotally mounted one end of a rod 217 which is threadedly secured to a block 218. The block 218 is pivotally connected at 219 to an arm 221 formed as an integral part with a rockshaft 222. This shaft has oscillating movement within a bearing 223 projected outwardly from the chamber cover 62 and in a similar bearing 224 projecting outwardly from the chamber housing 61. The shaft 222 is oscillated by a hand lever 231 which is secured to its lower end. This hand lever provides the manual control of the clutch 151 and its end is formed with a hand grip 232. The lever has an arcuate extension 233 on one side (Fig. 9). In the unclutched position of the hand lever 231 as shown in Fig. 9, the motor 141 can be started.

Motor 141 is suitably wired in an electrical circuit which will be hereinafter fully described and these wires lead into a switch box 241 (Figs. 9 and 12) which has a start button 242 and a stop button 243. When the start button is engaged the switch in the switch box 241 is closed and electrical energy may be brought into the motor to cause its rotation. When the stop button is pressed the current flowing in the switch box 241 is interrupted and the motor comes to a stop.

A lever 245 (Figs. 9, 10 and 12) is pivoted at 246 to a tubular housing 247 which is formed as an integral part of a hollow shell 248 bolted at 249 to the chamber housing 61. An arm 251 of the lever 245 projects over the stop button 243 when the hand lever 231 is in unclutched position and a projection 252 formed on the end of the lever at such time rests over and against the end of the arcuate projection 233 of the hand lever. This position of the lever 245 leaves the start button unrestricted (Fig. 12) and the hand lever 231 cannot be moved from its unclutched position as long as the projection 252 of lever 245 is in the way. The motor can, therefore, be started by engagement of the switch button 242 and completion of the electric circuit through the motor.

The lever 245 is provided with a hand grip 253 and the part of the lever on that side of its pivot is heavier than the arm side 251 and gravity holds the lever to normally cover the stop button 243 unless prevented by lever 231. After the motor has reached its speed without load the lever 245 is manually swung from the position illustrated in full lines in Fig. 12 into the position illustrated by the broken lines in that figure. With the extension 252 out of the path of the extension 233 of the lever 231 the latter is moved by engagement with its hand grip 232 and the clutch spring then being released operates to connect the rotating sprocket 149 with the main shaft 195, this action starting the operation of the machine. In its raised position the lever 245 is held against further movement by a stop lug 255 formed on the lever striking a projection 253 of the housing 247.

It will be observed that as long as the lever 245 is out of engagement with the lever 231, its arm 251 covers the start button 242. If, therefore, the lever is moved to permit throwing in of the clutch by operation of the hand lever 231, the motor can not be started. If there should be a failure of electrical energy or if anything happens to stop the motor, it and the entire machine might stop with the hand lever 231 in clutched position. The start button 242 being

covered at such a time would then prevent restarting of the motor. To uncover the start button the clutch must be disengaged. This is the safety feature which prevents the starting of the motor under a load.

Vacuum maintenance

During the normal operation of the apparatus, air is continually exhausted from the interior of the vacuum chamber 71 and a substantially uniform degree of vacuum maintained, pocketsful of air brought into the chamber by the entrance valve with the cans and by the exit valve, being immediately carried away or exhausted. A vacuum gage 261 (Fig. 4) may be used for visually indicating this degree of vacuum within the chamber.

In this removal of the air a suitable source of vacuum is connected with the interior of the chamber and such connection may be done in any suitable manner. In the drawings, a pipe 262 (Figs. 1 and 10) indicates such vacuum connection which may be made with a pump, a vacuum tank or other vacuum source. A hand valve 263 is preferably interposed in the vacuum pipe system 262 and by means of a handle 264, this pipe line may be kept open or closed as desired.

A chamber 265 is located inside of the tubular housing 247 (Figs. 9 and 13) and is in communication with a similar chamber 266 enclosed within the shell 248. An opening 267 formed in the vacuum chamber housing wall 61 provides a free passage for the air from the vacuum chamber 71. A predetermined minimum of vacuum is necessary to keep the machine operating and if the vacuum in the vacuum chamber should fail to remain as high as this predetermined vacuum point an automatic device stops the machine.

This automatic feature is under the control of 40 a sylphon bellows 271 (Fig. 13) which is enclosed in a chamber 272 formed in an extension of the housing 247. The lower wall of this sylphon bellows is secured to the upper end of a sleeve 274 bolted to the extension of the housing 247 45 and this sleeve encloses a movable rod 275 associated with one of the electric stop devices which will be fully explained after the operation of the electric circuit for the apparatus is discussed. A head 276 formed on the upper end of the rod 50 275 is secured to the upper wall of the sylphon bellows 271 and has sliding movement within the upper end of the sleeve 274.

Can body timing mechanism

The preceding description is in the nature of a general consideration of certain of the machine parts not closely associated with the actual operations performed upon the can body or the can cover. The description which immediately follows will be particularly directed to the course of a can body or a can cover through the various operations of the machine. Attention, therefore, will first be directed to the timing unit which receives an open-ended can and advances it into the machine while timing it for succeeding operations. Reference should now be had to Figs. 5, 6 and 16.

Open-ended cans 291 are received in untimed order upon a constantly rotating disc which comprises an outer ring 292 bolted at 293 to a disc body 294 in turn secured at 295 to a sleeve 296 keyed at 297 to an inner sleeve 298 mounted upon a stationary vertical shaft 299. This timing disc is supported upon a roller bearing unit 301 which

is carried in the upper end of a hood 302 mounted upon and bolted at 303 to a swinging support extension frame 304 which constitutes a part of the frame associated with the entrance valve of the apparatus.

This extension frame 304 is secured at 305 (see also Figs. 4, 17 and 18) to a swinging, hinged valve frame 306 which, at a position above its connection with the frame 304, spreads outwardly and upwardly in arms 307 adjacent the unhinged side and as a web 308 on the hinged side. At its upper end the web 308 is integral with a vertical wall 309 (Fig. 18) and lugs 311 project rearwardly from this wall. These lugs provide pintle bearings for hinging connection with a vertical shaft 312 which is held in arms 313, 314 formed as integral parts of a bracket 315 (Fig. 6) bolted at 316 to the outer wall of the chamber housing 61.

This frame 306 and frame sections 307, 308, 309 constitute a hinged support not only for the timing disc but also for the entrance valve, the can cover magazine, the can marker and all parts associated therewith. To permit easy swinging of the frame and its parts on the shaft 312 and to support the weight of such a mass of metal, the support extension frame 304 is projected outwardly at 321 (Figs. 1, 4 and 5) and provides engagement for a roller carriage frame 322. This frame is secured preferably at 323 to the frame part 321 and carries two roller pins 325 on which are severally mounted two supporting rollers 326 substantially protected by housings formed in the carriage frame 322. These rollers 326 provide anti-frictional supports for the swinging valve frame and parts carried thereby and are adapted to roll over a semi-circular track 328 supported upon the central section 54 of the base 61.

The arms 307 (Figs. 6 and 17) are extended outwardly in a plate section 331 which is slotted at 332 and which engages a wall 333 of a projection formed on the chamber housing 61. This swinging valve frame and parts carried thereby is in position for operation of the machine when the member 331 engages the wall 333 and in order to hold it in clamped position, there is provided a pair of hand clamps 334 which are threadedly secured to eyes 335 pivotally mounted on pins 336 held in lugs 337 projecting outwardly from the wall part 333. These eyes 335 are adapted to be inserted within the slots 332 when the swinging valve frame is in operating position, after which the hand clamps 334 are drawn into tightly threaded position upon the ends of the eyes.

The timing disc is provided with a series of can spacing fingers 351 (Figs. 5 and 16) which are preferably provided with vertically extending stems 352 mounted for oscillation in bearings 353 formed in the disc body 294. These bearings are equally spaced and are arranged around and at equal distances with respect to the shaft 299 and each stem below its bearing is surrounded with a spring 355 confined between the bottom wall of the bearing and a nut 356 threadedly secured to the lower end of the stem. One end of each spring 355 engages a pin 351 located in the bearing 353 and the opposite end of the spring is confined by a hook 358 secured to the nut 356 and this mounting of the spring tends to turn the stem in one direction.

Each finger 351 is also provided with an upwardly extending projection 361 which carries a pin 362 upon which a cam roller 363 is rotatably mounted. This cam roller is utilized to oscillate

the finger 351 on the axis of its stem 352, the cam movement applied to the roller being opposed to the movement of the spring 355. In other words the spring tends to hold each finger in a forward or outward position.

The shaft 299 is stationary and is supported in a boss 365 formed in a lower cap member 366 bolted at 367 to the undersurface of the frame 304. A nut 368 threaded on the end of the shaft draws it rigidly within the boss 365. The shaft 299 at its upper end carries a cam 371 which is located directly above the end of the inner sleeve 298, a central hub section 372 of the cam extending over the upper end of the disc sleeve 296.

A double-walled cam track 373 is traversed by 15 the roller 363 and for slightly less than half of its length, its inner wall is relieved as at 374 (Fig. 16). The spring 355 of each finger stem 352 normally holds its cam roller 363 outwardly against the outer wall of the groove of the cam 20 track 373 while the timing disc with its fingers and cam rollers are moved in a circular path of travel around the stationary shaft 299 and cam 373.

The cans 291 enter the machine at station A 25 (Figs. 6 and 16) and as they are advanced with the timing disc are spaced by the fingers 351 so that only a single can is between two adjacent fingers. In reaching this spaced condition some of the fingers are depressed as cans roll back into 30 place behind such fingers and it is during this time that the cam rollers 363 move into the widened cam space 374 as their springs 355 yield. In this way the cans are timed with the operations of the machine. At the same time the 35 cans are accelerated by action of the fingers 351 up to the desired speed and time relation, this being effected through the cam control of the fingers.

These cans are confined within a path of travel 40 by an outer guide rail 375 (Figs. 1, 5, 6 and 16) which is supported upon a bracket 316 bolted to the extension frame cover 302. They are also guided from the inside by an inner guide track formed on a peripheral wall 377 of a cover member 378 mounted upon the upper end of the shaft 299. A collar 379 is secured to the upper end of the shaft 299 and is bolted to the cover member 378, this permanently holding the latter in stationary position.

To effect the rotation of the timing disc, rotation is applied to the inner sleeve 298 and for this purpose it carries a bevel gear 381 which is adapted to receive rotation through a geared connection from the main shaft 195. A spacing sleeve 382 is disposed upon the inner sleeve 298 and is confined between the roller bearing 301 and the upper end of the hub of the gear 381. A second spacing sleeve 383 is also located on the inner sleeve and is confined between the lower end of the 60 hub of the gear 381 and a roller bearing unit 384, the movable part of which is confined by a nut 385 threadedly secured to the end of the inner sleeve.

The stationary part of the roller bearing unit 65 is confined within a collar 386 extending through a boss 387 formed in the extension frame 304, a nut 388 threadedly engaging the collar for this purpose. This construction provides a more rigid support for the lower end of the sleeve 298 and permits its rotation on the stationary shaft 299.

The gear connection between the bevel gear 381 on the sleeve 298 and the main drive shaft 195 will now be considered (see Fig. 5). A bevel 75

pinion 391 meshes with the gear 381 and is mounted upon a horizontal shaft 392. This pinion normally rotates with the shaft but is not keyed to it, a slip clutch being provided to permit turning of the shaft within the pinion in the event of jamming or other abnormal conditions. For this purpose the hub of the pinion 391 carries a plate 393 which is provided on its outer face with one or more seats 394 for one or more clutch buttons 395 carried in the flange of a sleeve 396 secured to the shaft 392 in engagement with the plate. The sleeve is slotted at its end at 397 and a clamp nut 398 is threaded upon the sleeve and draws the slotted end into tight holding engagement with the shaft.

The shaft 392 is shouldered and pinion 391 and plate 393 are confined against the shoulder by a thrust bearing 399 held on the end of the shaft by a nut 401. A spring 402 (see also Fig. 4) is confined between a collar 403 mounted on the sleeve 396 and resting against its flange and a nut 404 threadedly secured to the end of the sleeve. This spring normally holds the clutch button 395 within its seat 394 and normally locks the pinion 395 with the shaft 396. If an obstruction of any kind resists free turning of the pinion the clutch button 395 slips out of its seat, the spring 402 permitting this action.

Shaft 392 also carries a bevel gear 405 secured to its opposite end. This shaft is mounted in bearings which are located outside of the hubs of the pinions 391, 405. For this purpose a bearing unit 406 is disposed on the hub of the pinion 395, its stationary element being confined within the extension frame 304 and held in position by a washer 407. In a similar way a roller bearing unit 408 is interposed between the hub of the gear 405 and the extension frame 304, a collar 409 being used to hold the parts in position.

The gear 405 meshes with a similar gear 415 which is secured to the lower end of a vertical shaft 416. This shaft supports the entrance valve and is journaled in a bearing unit 417 carried in a hub part 418 of the swinging valve frame 306. The upper end of shaft 416 is journaled in a bearing 419 (Figs. 4 and 17) formed in the arm 307 of the swinging valve frame and in addition a roller bearing unit 420 is also used at this position. A cap member 422 is secured to the frame arm 307 enclosing the bearing unit and holding it in place. Access may be had to the lower gears 405, 415 through an opening in the surrounding casing which is preferably closed by a plate 423.

The shaft 416 carries a gear 431 (Figs. 4 and 7) which is confined within a housing 432 carried by the frame 306. The gear 431 meshes with a pinion 433 which is keyed to the upper end of a vertically disposed shaft 434 (see also Figs. 8 and 41) which is journaled at its lower end in a ball bearing unit 435 contained within a casing 436 secured at 437 to an auxiliary casing 438 formed inside of and as an integral part of the lower casing 52. A second ball bearing unit 441 surrounds the upper end of the shaft 434 and is carried in a casing cover 442 mounted upon and bolted to the casing 436. The two bearing units 435, 441 are held in position by cap members 443, 444.

A gear 445 is mounted upon the shaft 434 and normally turns with it, the connection being made through a slip clutch which allows for disconnection at this point in the event of abnormal conditions affecting free rotation of the shaft.

This clutch comprises a ring 447 which is apertured at one or more places to confine one or more clutch balls 448 adapted to seat in one or more depressions 449 formed in the lower face of the hub of the gear 445. The clutch ball or balls are backed-up by a washer 451 which is yieldingly held against the ring 447 by a spring 452 surrounding the shaft and confined by a nut 453 threadedly secured to the shaft. A thrust bearing unit 454 is interposed between the upper face of the hub of the gear and a shouldered part of the shaft 434.

When an abnormal condition blocks the shaft 434 the gear 445 is disconnected by a yielding of the spring 452 which allows the clutch ball 448 to snap out of its seat or pocket. The gear then turns upon the shaft. The washer 451 moves downwardly away from the ring 447 at such time and this movement is utilized to operate one of the electric stop devices. This will be herein-after fully explained.

The gear 445 (Figs. 8 and 41) meshes with a gear 461 which is keyed to a short stub shaft 462 journaled above in a roller bearing unit 463 confined in a cap 464 secured to the casing cover 442 and below in a similar bearing unit 465 confined in a cap 466 bolted to the casing cover 436. The gear 461 is driven by connection with the main shaft 195 by meshing with a gear 467 (Figs. 3, 4 and 8) which surrounds the lower end of the shaft 195 and which is mounted directly upon a stem 468 of a second gear 469. There is vertical sliding connection between the lower end of the main shaft and the stem of the gear 468, a feather 471 being carried in the gear and sliding within a suitable featherway in the shaft. This construction permits easy assembly of the parts.

The indirect support for the lower end of the shaft 195 within the bearing units 199 can now be explained in detail. The rotating elements of these two units are carried directly by the stem 468 being clamped to operate within the stationary elements by a nut 472 threadedly secured to the upper end of the gear stem. These stationary bearing elements are pocketed in the casing 436. A cap 473 secured to this casing covers the upper bearing 199. A can 291, passing between the wall 371 and the guide rail 375 (Figs. 5, 6 and 16) in its travel with the timing disc from position A is discharged fully timed into a pocket of the entrance valve at a position indicated by the letter G.

Entrance valve mechanism

This entrance valve is mounted upon the shaft 416 and comprises a valve body 475 (Figs. 4, 5, 6 and 16) having a cylindrical outer wall and inner partition walls, the latter formed to provide a series of spaced can receiving pockets or chambers 476. There are six of these pockets in the present embodiment as disclosed in the drawings.

This valve body 475 is secured to a bottom plate 477 which rests upon and is bolted to a flange 478 of a sleeve 479 which forms an integral part of the gear 434. Bolts 481 secure the valve body, its bottom plate and the flange 478 together as a single unit. The valve body is also formed with a top plate 482 which is projected upwardly at its center in a boss 483 for engagement with the shaft 416.

Each valve pocket chamber 476 is much larger than a can and separate can pocket members recessed to form closely fitting can seats or holders are located within the pocket chambers. A lower can receiving plate 485 (Figs. 4 and 16) 75

constitutes one of a pair of pocket members for each chamber and is secured to an inner partition wall of the valve. This plate is open at its outer periphery and the cans 291, as they leave 5 the timing disc ring 292 (position G, Fig. 16) pass into the recessed pocket of the plate.

A similar plate member 486 is mounted in the upper section of the pocket chamber 476 and is formed with a peripheral recess corresponding in 10 shape and size and also aligning with that of the lower plate 485. The upper plate 486 is located directly beneath a spacer block 487 both members 486, 487 being clamped to the upper wall 482 of the valve body by a bolt 488 and a locknut 489. 15 (Fig. 4.) The aligned recessed pockets of the members 485, 486 insure that the can 291 is properly positioned within the turret and when fully seated is in alignment with and directly beneath a can cover which has just been inserted into the 20 valve chamber and into a cover pocket formed in the member 486. This placing of the cover will be hereinafter fully described.

This entrance valve provides an air-tight closure for the opening 131 of the vacuum chamber 25 and constantly rotates to receive cans from the timing disc and to move them into the vacuum chamber without permitting loss of vacuum within the chamber. To effect the necessary seal between the moving periphery of the valve 30 and the wall of the vacuum chamber housing 61, a flexible or floating valve seat is provided which frictionally engages the valve.

This valve seat member comprises an annular relatively flat outer frame 501 (Figs. 4, 6, 16 and 35 17) which joins with a bulged cylindrical section extending into the vacuum chamber. This section has spaced top and bottom walls 502, 503 which merge into an inner cylindrical wall 504. A central section of this cylindrical wall provides 40 the valve seat proper which closely engages the periphery of the entrance valve throughout substantially half of its extent. An opening 505 cut through this section allows the cans 291 to pass from the valve into the vacuum chamber.

45 A yielding engagement is provided between the valve and its float valve seat, the frame 501 being formed on its inside face with a channel 506 in which is disposed a flexible tube 507, one face of which engages the outer wall of the vacuum 50 chamber housing 61 surrounding the opening 131. This tube 507 is adapted to be filled with air at any desired pressure and this pressure in the tube determines the amount of pressure exerted by the valve seat on the valve. The usual 55 form of automobile tire air valve and stem, designated by the numeral 508 (Fig. 17) may be used.

Adjacent the can entrance side of the valve seat frame 501, there is disposed a hinged valve cover 60 leaf 521 (Figs. 6, 16 and 17) which also engages the peripheral cylindrical wall of the entrance valve and acts as a combined valve lubricating and valve cleaning device. It is hinged at 522 to the outer edge of the valve frame part 504 65 and is formed with an inner concave valve engaging wall 523. It is held in valve engaging position by an adjustable link 525 having an end 526 which may be inserted in a pocket formed by 70 a lug 527 projected outwardly from the surface of its outer wall.

The opposite end of link 525 is pivotally connected at 528 to a block 529 pivoted at 531 to a lug 532 formed on the plate section 331 of the 75 swinging frame arms 307. When inserted

position, this link 525 holds the cover leaf 521 against the valve as illustrated in Fig. 16.

When the entrance valve is used with cans filled with products containing syrup such as fruit juices, some of this syrup will lodge on its periphery and if allowed to accumulate will interfere with the free rotation of the valve. Provision is made for introducing a suitable liquid solvent, such as water to the engaged face of the valve leaf 521 in such a manner as to distribute it over the engaging surfaces of valve, valve seat and cover leaf.

Such a liquid may be supplied from a pipe 535 (Fig. 17) in small quantities, the discharge end of the pipe preferably permitting only an occasional drop which will fall into a cup 536 mounted upon the top of the cover leaf 521 adjacent its free edge. An opening groove or channel 537 may be made in the body of the valve cover leaf to conduct the liquid from the cup to the leaf cover 20 face. Sufficient of the liquid is in this way distributed with the assistance of gravity by the rotating valve so that any foreign matter on the engaged valve surfaces is properly dissolved.

The valve surfaces are then wiped and lubricated in the following manner. An oil cup 541 is mounted on the cover leaf 521 and its interior communicates with a passageway 542 (Figs. 17 and 20) the lower end of which terminates in a vertical groove 543 (see also Fig. 21) cut along the 30 inner surface of the cover leaf. An absorbent wick 544 of any suitable material is preferably embedded in the groove and a lubricant from the cup 541 is allowed to flow downwardly by gravity and saturate the wick. The surfaces of the rotating valve passing this wick are thus wiped and lubricated, insuring continued free movement of the valve within its seat. This wick is preferably 35 confined within a holder 545 secured by a bolt 546 to the cover leaf. Glycerine has been found 40 to be suitable as a lubricant when used in this way.

The cylindrical wall part 504 (Figs. 4, 6 and 16) of the float valve seat forms the partition between the valve pockets and the vacuum chamber and 45 while passing along this wall, the pockets are progressively vacuumized. To permit such progressive vacuumization radially disposed ports 551 are cut through the wall 504 and provide a communication between the vacuum chamber 50 and the pocket of the valve. These ports are spaced from one another and are of sufficient restricted dimension to effect the desired gradual removal of the air from the pocket and from the can without disturbance of the degree of vacuum 55 within the chamber.

Can cover feed mechanism

During this passage of the can within the entrance valve it moves from station G (Fig. 16) 60 to a position adjacent the opening 505 in the wall 504 (station H). At the same time a can cover is also being conveyed in the same pocket but held in spaced relation above the can. This can cover is automatically fed only at such time as there is a can to receive it. The feeding of the can cover will now be described.

The magazine for the can covers, the cover feeding devices and associated parts, as well as the marking devices are carried in a what will be 70 called a magazine supporting frame which is adjustably mounted upon the swinging valve frame part 309. This adjustment is in a vertical plane and permits an accurate positioning of the parts so that the proper horizontal path of travel of the 75

can cover may be had as it is removed from the magazine, passed through the marking station and finally deposited into a valve pocket in the entrance valve 475.

5 To afford such a mounting the valve frame part 309 is formed with a dove-tail projection or shoulder 575 (Figs. 16 and 18). The magazine supporting frame comprises a frame part 576 which is formed with a vertically extending slot 577, the walls of which are adapted to closely fit the walls of the dove-tail part 575. A locking key bar 578 is used to lock the parts together and rests within a second vertically extending slot 579 formed in the frame 576 adjacent the slot 577. This key bar has one side beveled at 581 which engages one side of the shoulder 575. Bolts 582 threadedly engaged within the frame part 576 hold the key bar in locked position (see also Fig. 19).

20 In order to accurately control and hold the frame 576 during adjustment, there is provided a hand wheel 585 (see also Figs. 1 and 6) and an adjusting bolt 586 which are secured together, the latter being freely rotatable within a bracket 25 587 bolted at 588 to the top of the frame 309 directly above one of the lugs 311. The bolt 586 below the bracket threadedly engages the frame part 576 and turning of the bolt by its hand wheel raises and lowers the magazine supporting frame. 30 Such adjustment is made while the key bar is loose and after the desired position has been reached the bolts 582 are tightened and the key bar locked.

35 The frame 576 below merges into a hollow column 591 (Figs. 18, 19 and 22). This column is extended laterally adjacent its bottom into a shell section 592 open at both top and bottom. Parts of the marking device are contained within the column 591 and the shell part 592 of the magazine frame provides a support for the cover magazine and parts associated therewith. An end feed post 595 is carried by and secured at 596 to the shell part 592. This post is hollow and houses certain parts of the cover feeding devices.

40 45 The post 595 is enlarged at its upper end into a gear housing 597 (see also Fig. 23) which supports an intermediate housing 598 open at its upper end and which is closed by a housing cover 599 secured thereto. This cover 599 carries the magazine proper, an apertured magazine plate 601 being bolted to and extending into a central opening 602 formed in the cover. The magazine plate 601 carries vertically extending guide rods 603 which retain the can covers, designated by 50 55 the numeral 605, in stacked position within the magazine, this location being indicated by the letter B in Figs. 16 and 32.

60 The can covers 605 when in the stack within the magazine are supported from below with the lowermost cover supported on one side by a stationary block 611 (Figs. 16, 22 and 28) which is secured to the underside of the housing cover 599. A curved pocket 612 is formed in the block in which the lowermost covers are located, a shoulder 613 being at the base of the pocket. At the 65 opposite side or diametrically across from the shoulder 613, the lowermost cover rests upon an annular ridge 614 (see also Figs. 24 and 25) formed in the periphery of a separator disc 615. The disc 615 is secured on top of a separator body 616 which is keyed to the upper end of a 70 vertically extending sleeve 617 journaled in roller bearings 618 arranged in a collar 619 bolted to and resting upon the intermediate housing 598. 75 The lowermost cover on the ridge supported side

is also normally supported on a tongue 621 formed on the forward end of a trip finger 622 (Figs. 28, 32, 33 and 34). The finger 622 is associated with a no-can no-end trip device and is adapted to be moved out of cover supporting position only when a can 291 enters the machine. The operation of this no-can no-end trip device and the effect of a can tripping the device will first be described.

5 10 15 A trip lever 625 (Figs. 16 and 27) is pivoted on a stud 626 carried on the bracket 376 which supports the guide rail 375. Lever 625 is formed with a can engaging section 627 which normally rests within the path of travel of a can 291 as it is conveyed by the timing disc 292 from station A. As a can engages this section of the lever it oscillates the lever on its pivot 626 and moves it from the position illustrated in Fig. 16 into that of Fig. 27.

20 25 30 A spring 628 is confined within a bore formed in an arm 629 of the lever and this spring is compressed when a can moves the lever. A spring barrel 631 is located within the bore, one end resting against the spring, the other end in contact with an extension 632 formed in the guide rail 375. A third arm 633 of the lever 625 connects with a link 634 as at 635 and the opposite end of the link is pivotally connected at 636 to one arm of a lever 637 (Figs. 18 and 27).

35 40 45 Lever 637 is pivoted on a screw 638 held in a depending part 639 of the gear housing 597. The opposite arm of the lever 637 is pivotally connected at 641 to one end of a link 642 which is pivotally connected at 643 (see also Fig. 22) to an arm 644 secured to the lower end of a shaft 645 mounted for oscillation within the sleeve 617. The upper end of the shaft 645 (Figs. 16, 22 and 32) carries an arm 646 which is pivotally connected at 647 to the finger 622. The finger 622 is retained between posts 651 (Figs. 33 and 34) which extend downwardly from a plate 652 which is screwed to the undersurface of the cover 599. This mounting permits free sliding movement together with a slight rocking movement of the finger back and forth between the posts.

50 55 60 The lowermost can cover 605 resting in the stack within the magazine is released from the support of the ridge 614 by rotation of the separator disc 615. This ridge extends only part of the way around the disc and makes such a release possible. As long as the can trip lever 625 remains in unactuated position (as shown in Fig. 16) the finger 622 remains in the position illustrated in Fig. 28 where its projection 621 supports one side of the stack of covers irrespective of whether there is an additional support by the ridge 614 of the disc 615.

65 70 75 When, however, a can passes into the machine and actuates the lever 625, the finger 622 is withdrawn from engagement beneath the stack of covers and at such time the lowermost cover is completely under the control of the separator disc 615. It is while the finger 622 is in its withdrawn position that separation and feeding of the cover takes place. This will now be described.

The ridge 614 extends substantially through 180° along the periphery of the disc 615 and between the ends of the ridge the disc's upper edge is cut away or grooved in a set-back peripheral wall 655 (Figs. 24, 25 and 29). The disc body 616 on which the separator disc is mounted is provided with a flange 656 which is located directly beneath the periphery section 655 of the disc and the upper surface of this flange at one end extends upwardly in an inclined track 657. Rotation of disc and body 615, 616 carries the

groove section 655 adjacent the edge of the lowermost can cover which lowers on that side and moves to the position illustrated in Fig. 29, where it rests upon the flange 656 of the rotating body.

5 A separator knife edge 658 is formed in the periphery of the disc 615 adjacent one end of the ridge 614 and this edge engages above the lowermost can cover and beneath the can cover directly above and lifts the latter with the stack 10 of covers along one side (see Fig. 30). Rotation 15 of the disc continues and the ridge 614 then picks up the weight on one side of the stack as before. By this time the can 291 has passed the projecting sections 627 of the lever 625 (Fig. 27) and the 20 spring 628 restores it to normal position, this return movement being transmitted to the finger 622 which moves forward and again projects its 25 tapered edge 621 beneath the stack of covers.

As long as the lever 625 remains inactive, that 20 is, with no cans passing into the machine, the finger 622 prevents further separation of a cover from the magazine. The grooved part 655 even when moved beneath the stack of covers, with the continuing rotation of the disc 615, has no 25 effect upon the lowermost cover since the latter is not allowed to move down onto the flange 656.

Following this separation of one side of the lowermost cover from the stack of covers, the rotating disc body 616 moving beneath the cut-out 30 cover reaches a position where its flange 656 terminates in an inclined surface 659 (see Fig. 25). The supported side of the cut-out cover rides down this incline and tilts to such a position that its lower edge is engaged beneath an inclined 35 surface 661 of an arcual projection 662 formed on the disc body, this position being illustrated in Fig. 31. It is now in position to be engaged by a cover feeding device mounted adjacent and beneath the magazine.

40 The disc 615 and its body 616 is continually rotated by a gear train which will now be described. The sleeve 617 (Figs. 22 and 23) is keyed to and carries a gear 665 which is located inside the gear housing 597. The gear 665 meshes with an idler pinion 666 mounted on a stud 667 secured 45 to the housing 597. The pinion 666 in turn meshes with a gear 668 formed on the upper end of a stem 669 which is journaled in a bearing 50 671 formed in the housing 597. This shaft 669 also carries the mechanism associated with an electrical stop detector which is used to indicate failure of supply of can covers within the magazine. This feature will be described at a later time and in connection with the description of 55 electrical wiring and the electrical stop devices.

The gear 668 is also in mesh with a gear 672 which is keyed to a vertical shaft 673 rotating inside of the end feed post 595. The gear 672 is also enclosed within the gear housing 597 and its shaft 673 is journaled above in a roller bearing unit 675 carried in the intermediate housing 598 and below in a similar bearing unit 676 carried in a cap 677 bolted upon the end of the shell part 592.

60 The shaft 673 is continually rotated by the use of spiral gears, a gear 681 (Figs. 8 and 22) keyed to the lower end of the shaft meshing with a gear 682 formed on a short stub shaft 683 (see also Fig. 19) located in the lower end of the column 591. One end of the shaft 683 is journaled in a bearing unit 684 carried in a cover member 685 bolted to the column. A cap 686 is secured to this cover member. The shaft 683 is journaled at its opposite end in a bearing unit 687 which is 65 carried in the lower end of the column 591. A

column extension housing 688 is secured to one side of the lower end of the column 591 and encloses a pair of bevel gears 691, 692, the former being keyed upon the shaft 683.

The gear 692 is mounted upon the lower end 5 of a vertically disposed shaft 693 which projects into the column extension housing 688 and is rotatably carried thereby. For this purpose, the gear 692 is formed as an integral part of a sleeve 694 which surrounds the lower end of the shaft 10 693 and is keyed to it. This sleeve is journaled in roller bearing units 695, 696 keyed respectively in the extension 688 and in a cap 697 bolted to the lower end of the extension housing.

The upper end of shaft 693 (Figs. 7, 8 and 19) 15 extends into the swinging frame 304 and the housing 432 being confined within a circular extension 698 of the former. Shaft 693 is journaled in a bearing unit 701 carried in the frame part 693 and in a bearing unit 702 carried in a cap 20 703 bolted to the frame part 698. A gear 704 is keyed to the shaft 693 between the bearing units and is in mesh with the gear 431 previously described. All of the shafts, gears and associated 25 parts just described are supported by the swinging valve frame 304.

The cut-out cover in its inclined position is at the entrance end of a curved and inclined path of travel which is provided by spaced grooves. This path leads to a marking station. 30 A rotating disc is used for moving the cover along this path and the disc rotates in a plane below the hind side of the inclined cut-out cover. An element on the disc engages the cover as soon as it comes into cut-out position and the travel 35 begins.

During the downward and curved movement of the cover into the marking station it is partially leveled from its inclined position and is also gradually shifted further away from the 40 disc center. Upon reaching the marking station it has been laterally shifted to a position where its inner edge is beyond the peripheral wall of the cover engaging element. It thereupon comes to rest and the disc continues to move without 45 effecting the similar movement of the cover. The marking operation takes place while the cover is at rest.

By the time the marking has been completed 50 other elements carried by the disc and extending beyond its peripheral wall engage and sweep the marked cover on to the next station. This travel of the cut-out cover from alignment with the magazine at station B will now be described.

When the can cover is in the position illustrated in Fig. 31, its upper side rests on the shoulder 613 and its lower side rests on the top of a guide rail 711 (see also Figs. 16, 22 and 32). This guide rail is bolted at 712 to the housing 597 and at 713 to a lug 714 formed as an integral 60 part of the magazine frame section 576. The shoulder 613 is at the upper end of an inclined groove 715 formed in the block 611. The lower or outer side of the cover on the guide rail 711 65 is at the upper end of an inclined groove 716 formed in the guide rail.

The feeding devices for moving the cover through the inclined grooves 715, 716 comprise a cover feeding disc 721 (Figs. 16, 22, 26 and 32) located to one side of but extending beneath the 70 cut-out cover. This disc is mounted upon and carried by a disc body 722 which is keyed to the upper end of the shaft 673. This disc body is provided with a series of vertical holes 723 which are spaced around a circular line concentric with 75

the center of the shaft 673. The disc 721 is provided with a similar number of holes 724 which are also disposed circularly about the shaft 673 but are spaced at slightly different intervals from 5 the openings in the disc body.

A vernier adjustment by which the disc may be accurately positioned relative to the disc body is made possible by the use of a pin 725 which is carried on the outer end of a vernier arm 126 10 pivoted upon and held by a bolt 727 threadedly engaging the upper end of the shaft 673. This pin is located in the proper holes and forms the adjusted connection between the parts 721 and 722.

15 A pair of diametrically opposed hooked sections 731 (Figs. 26, 31 and 32) are formed on the disc 721. Each hook constitutes the forward edge of a ridge segment 732 which is indented in its outside wall to provide a groove 733 for a 20 purpose hereinafter described.

To form such an edge each ridge segment 732 is cut back in an inclined section 734 (Fig. 26) which merges into a horizontal section 735 at a 25 lower level. Each section 735 is directly beneath a hook 731 and forms the floor of its associated groove 733.

The separation of the lowermost cover from the magazine and the dropping down of its outer edge places it in the path of one of the advancing 30 hooks 731. The cover at such times lies over the inclined section 734 of the disc, there being ample clearance between cover and disc adjacent this inclined section. The hook 731 engaging the cover edge sweeps it along the inclined 35 35 grooves 715, 716, these grooves directing it away from the center of the disc.

At position C (Fig. 16) its inner side leaves the groove 715 and rests upon the section 734 of the feeding disc. A slight distance further on 40 (Fig. 32) it engages a pin 742 (Figs. 32, 35, 36 and 37) which projects downwardly beneath the magazine cover 599. This pin is an integral part of a block 743 which has sliding movement for adjustment purposes within a groove 744 45 formed in the cover 599. A stem 745 projects upwardly from the block 743 and extends through an elongated slot 746 (Figs. 6, 35 and 36) formed in the cover member 599. By shifting of the block 743 in the slot 746 its pin 742 is accurately 50 adjusted for position, a nut 747 threadedly secured to the end of the stem 745 rigidly holding the parts.

The can cover 605, in engaging the pin 742 comes opposite an offset section 751 (Fig. 32) cut 55 in the inner face of the guide rail 711 and formed as a continuation of the groove 716. This offset merges into a groove 752 which is concentric with the axis of shaft 673 but farther from it than the grooves 716, 751. The cover 605 moves outwardly under a combined deflecting 60 action of the stationary pin 742 and the advancing hook 731 of the cover feeding disc. While still against the pin 742 its outer edge passes into the grooves 751 and 752 and the cover comes 65 to a momentary pause at the marking station D (Fig. 32).

The outer periphery of the cover 605 is now beyond the vertical wall of the groove 733 (Figs. 26 and 32) and the rotating feeding disc 721 70 sweeps by the cover. Throughout the next quadrant of movement of the disc 721, the cover remains in the same lateral position at station D.

The inner edge of the cover during this rest period is first supported on the horizontal surface 735 of the disc and is then supported on an

inclined continuation of the track designated by the numeral 755. The opposite or outer edge of the cover at this station rests on the bottom floor of the groove 752 which is of substantial width at this point. The marking operation will next 5 be described.

Can cover marking

The marking mechanism is carried upon the magazine frame 576 (Figs. 18, 19 and 32) and 10 embodies a stationary upper die and a movable lower die which cooperate with each other and with the cover interposed between their die faces to emboss the desired mark in the cover. These active die elements are carried in a removable 15 marking unit 761 which is inserted from one side of the machine and held in operating position for the marking operations upon successive covers passing through the marking station.

The front wall of the column 591 at its upper 20 end is extended outwardly in a shelf-like frame 762 which is cut away at its center and grooved along its sides to provide a pair of opposed guideways 763. It is into these guideways that the unit 761 passes when being inserted. The supporting frame 576 directly above the shelf 762 is cut away at 764 and it is in this opening that the removable marking unit rests when fully inserted. Above the opening the supporting frame is formed with a boss 765 on the underface of 30 which is secured an anvil plate 766. This is used to back up the stationary die element as will be hereinafter fully explained.

A latch pin 768 (Fig. 19) is located within a threaded nut 769 threadedly engaged into the 35 frame boss 765 adjacent to and outside of the plate 766 and this pin cooperates with a part of the unit 761 to hold it in inserted position. For this purpose the nut 769 is formed with a hollow stem 771 which encloses the sliding pin 768. The 40 upper end of the pin carries a head 772 which allows easy lifting of the pin and sliding within the stem 771 of the nut 769 when disengaging or unlatching the pin from the marking unit. A spring 773 surrounds the pin 768 and is confined 45 within the stem of the nut and normally holds the pin in lowered latching position when its lower end rests in a recess of the unit 761.

The detachable unit 761 comprises a yoke 775, the upper leg of which carries an upper stationary die member 776 which is held in place within the leg by a clamping plate 777. The die member 776 during assembly may be held within the yoke by a locating pin 778.

The lower leg of yoke 775 spreads outwardly 55 into a rectangular base 781 having opposed side walls extended into tongues 782 which slideably fit within grooves 783 formed in the shelf-like part 762 when the unit is inserted into the guideways 763. The top surface of the guide rail 711 at 60 station D is cut away or slotted at 784 (Figs. 19 and 32) and this removes the upper walls of the grooves 716, 751. An insert block 785 carried on the upper leg of the yoke frame 775 rests in this 65 slot and supplies this deficiency by guiding the can covers at that position and holding them in the guide rail grooves.

The forward end of the base 781 is cut through with a vertical channel 780 in which a sliding 70 lower die member 786 is located. This lower die is prevented from falling out by a spring pressed button 787 mounted in a retaining plate 788 screwed onto the front of the base 781. The inner end of the button is yielding held within 75

a vertically extending slot 789 formed in the front face of the die member 786.

During the insertion of the marking unit 761 the lower end of the die member 786 extends a short distance below the base part 781 (Fig. 18) and this extended part passes through the opening formed in the shelf 162. A tongue 191 is formed on the bottom end of the die 786 and this tongue engages within and slides along a slot 192 cut in the upper end of a crosshead 793 mounted for vertical movement within guideways 794 formed in the column 591.

The crosshead 793 is retained in its vertical sliding position within the guideways 794 by slide plates 795 bolted to parts of the column and is formed with a transverse cylindrical slot or seat 796 for the head of a pitman 797. This pitman moves up and down and carries the crosshead and the lower marking die with it. Pitman 797 is mounted on the upper end of a shaft 798 which has slight yielding or sliding movement within a bushing 799 threadedly engaged in an upper stem 801 of a crank arm 802 working on a crank section 803 of the shaft 683.

25 A compression spring 804 surrounds the shaft 798 and rests upon the upper end of the bushing 799 and is confined in position by an adjusting nut 805 threadedly secured to the upper end of the shaft 798. This construction insures a raising and lowering of the lower die 786 and at the same time provides a yielding element or cushion for the die which allows for variations in the thickness of the tinplate in the cover being marked.

The marking operation takes place when the lower die 786 reaches the end of its upper travel. In doing this it first engages the cover and lifts its lower side slightly to bring it into horizontal position then further lifts the horizontal cover to clamp it against the lower surface of the die 40 776 which at such time is backed up by the anvil plate 766. The upper surface of the die 786 is formed with the suitable male element 806 and the lower surface of the die 776 is formed with a corresponding female element 807. This cooperation of die surfaces embosses the proper mark upon the cover. The height of the slot 752 (Fig. 35) in the guide rail 711 and the height of the groove 133 (Fig. 26) of the disc 721 allows for this lifting of the cover just described. The marked cover is now ready for removal from station D.

To permit ready assembly of the crosshead 193 and its actuating mechanism the column frame 591 is open along its front side and this opening is preferably closed by a hinged door 811 (Figs. 55 18 and 19) which is mounted on hinges 812, the door being held in closed position by a clamping catch member 813.

During the marking operation just described the rotating disc 721 carries the inclined track section 755 by and beneath the cover and by the time the marking operation is completed a horizontal extension 815 (Fig. 26) of the track comes opposite the marked cover.

The upper wall of the groove 133 dips down at 65 816 from a position above the end of the inclined part 755 and above the beginning of the section 815 and this reduces the height of the groove 133 which merges into a narrow groove section 817 (see also Fig. 36). Section 817 in height is a little 70 more than the thickness of the cover. In other words the cover edge can slide freely in the groove.

The inclined track surface 816 acting on the inner edge of the marked cover 605 forces its inner edge downwardly into the position illustrated in 75 Fig. 36. In this lowered position the cover is in

a horizontal plane beneath the lower end of the pin 742. It is now ready for removal from the marking station E.

Can cover feed into valve

5

Projecting finger units carried on the disc 721 effect such removal. There are two of these units and one now engages the lowered cover. Each of the projecting finger units comprises a shelf 821 formed as an integral part of the disc 721, 10 the upper surface of this shelf forming a continuation of the track section 815. Toward the rear of each shelf the upper surface merges into an inclined part 822.

15 A feeding hook 824 is located upon each of the projections 821 and it is one of these hooks which engages behind the marked cover and sweeps it forward beneath the pin 742 and in a circular path of travel. Its outer edge passes along the groove 15 752 of the guide rail 711 and its inner edge is carried by and moves with the track section 815 of the disc. The moving cover upon reaching position E (Fig. 16) begins its entrance into the pocket 476 of the entrance valve turret 475.

20 Each can pocket member 486 of the cover seat unit within a turret pocket 476 is grooved at 831 (Figs. 4, 16 and 17) and the cover, reaching station E at the mouth of the pocket, is on the same level as this groove. When coming to this 25 position the inner edge of the cover engages the end of a guide rail 832 which is formed with a circular wall 833 concentric to the valve shaft 416.

25 The valve turret 475 and the cover disc 721 are so synchronized in their respective, rotative movements that a turret pocket 476 intercepts the path of travel of a cover coming into the position E, as just described, and as the valve pocket and the cover feeding finger progress together the cover 30 is moved into the pocket.

35 Guide rail 832 is formed with a vertical extension 834 which is secured by bolts to a frame section 835 projected upwardly from the cover housing 599 (Figs. 6, 16 and 32). Continued rotation of the feeding disc 721 moves the can cover from 40 positions E to F, the cover at such time rocking around the end of the guide rail. This causes the cover to move further into the turret pocket and at F its inner peripheral edge is tangent to the wall 833 of the guide rail 832. At position F 45 the cover is affected by three forces, the stationary guide rail, the advancing hook 824 of the feeding disc and the moving wall of the valve pocket (see Fig. 32 for this position).

50 The travel of the cover is further effected by the revolving valve, the hook 824 sweeping past the cover's edge. The cover rests in the grooves 831 of the turret pocket which support the cover in the same horizontal plane. What is now its outer edge passes along a groove 836 formed in the upper 55 corner of the wall 833. The wall 833 merges into a curved section 837 (Fig. 16) which is extended in an inwardly inclined wall 838, the groove 836 continuing along the upper edges of the wall parts 837, 838. This track of the guide rail crowds the 60 cover further into the valve pocket position G being an intermediate place where the cover is approaching the end of the guide rail. As it passes this end of the rail it comes into its fully inserted position.

Can and cover assembly

70

65 It will be understood that this cover resting in the grooves 831 of the valve pocket is in alignment with and spaced directly above a can 291 75

which just entered the same valve pocket as it passed a position intermediate stations E and G. From the end of the guide rail 832 the can and its superimposed, but spaced cover, are carried 5 adjacent to and swept along the inner concave wall 523 of the valve cover leaf 521. The can and its cover are carried by the valve through substantially 180° of travel when they reach a position H (Fig. 16) where they come opposite to 10 one of six pockets 841 (see also Fig. 6) of a rotating transfer turret 842.

It is while the valve pocket 476 is passing adjacent to the transfer turret pocket 841 that both can and cover are removed from the former and 15 positioned into the pocket of the latter. To effect this transfer, reciprocating fingers located in each valve pocket 476 are used. For this purpose there is provided a lower finger 845 (Figs. 4 and 16) and an upper finger 846. One of each upper and 20 lower fingers constitute a set for each valve pocket and the two fingers of each set are located upon a vertically disposed oscillating shaft 847.

Each shaft is mounted below within a bearing formed in the bottom plate 471 and above in a bearing 848 formed in the top plate 482. Finger 845 operates through an opening 849 cut in the guide member 485 and finger 846 extends into and moves within a slot 851 cut in the guide member 486. Each upper finger 846 at its free end is cut 30 away in a groove 852 in which the flange of the can and the edge of the cover rest and this allows engagement of the lower part of the edge of the finger directly against the body wall of the can when the finger moves it out of the valve pocket.

35 Movement of fingers 845, 846 is effected by oscillation of the shaft 847 and for this purpose each shaft at its upper end carries an arm 853 (see also Fig. 6) which is located directly above the bearing 848 and above the valve 475. Each arm 853 carries a cam roller 854 which during the rotation of the valve 475 traverses a cam slot 855 formed in the under surface of a cam 856 located on the shaft 416 and held in fixed position upon the frame part 307. A bolt 857 passes through the 40 frame 307 adjacent its bearing 419 and also through a spacing washer 858 located on the shaft 416 directly beneath and has threaded engagement within the cam 856. Cam 856 is provided with a peripheral flange 859 which extends over and outside of the upper end of the valve body 475.

45 The transfer turret 842 is continually rotated on a supporting column 865. This column surrounds the shaft 195 and is provided with a flanged base 866 which rests upon and is supported by the lower casing 52 with which it is connected. The upper end of the column 865 is formed with a flange 867 which is directly connected to the horizontal wall part 185 of the vacuum chamber housing 61. The column connections both below and above are air-tight joints, the inside of the column not being under vacuum but the outside is within the vacuum chamber 71.

50 The transfer turret 842 comprises a sleeve 868 (Figs. 3, 4 and 6) which is mounted upon the column 865, a bushing 869 being interposed between these members and providing a bearing element for the transfer turret. Sleeve 868 is outwardly 55 projected in a circular flange 871 which provides an upper element for the transfer turret. This turret is composed of two adjustable sections, the upper section 871 just mentioned being movable in a vertical plane to accommodate the height of can 60 passing through the machine.

The flange 871 supports a circular ring 872 to which it is bolted, the outer periphery of this ring being provided with six half-circular openings corresponding to the pockets 841 of the turret. These openings cut in the upper ring are grooved 5 at the top and bottom to provide seats 873, 874 respectively, for the can cover and the flange of the can. A protecting half-circular plate 875 is screwed onto the ring 872 and partially surrounds the turret pocket.

10 A can passing from the valve pocket into the pocket 841 of the transfer turret is centered by means of its flange entering the groove 874. In like manner the can cover in passing from its seat in the valve pocket is properly aligned in the 15 groove 873 where it is still centered over the can but is held in spaced position above it.

The lower part of the transfer turret 842 is mounted upon the lower end of the sleeve 868 and this comprises a turret body 878. A feather 20 879 is located in a vertical featherway 881 cut in the cylindrical wall of the sleeve 868 and also in the body 878 and prevents turning one upon the other while allowing vertical movement. This body 878 at its upper end is extended outwardly 25 as a flange 882 which is located beneath and is always parallel to the flange 871 of the sleeve. This flange 882 supports a lower ring 883 which is bolted to it and its peripheral edge like the edge of the flange above is provided with half-circular pockets 884, each pocket being in vertical alignment with its corresponding pocket in the ring 872. This half-circular opening or pocket 30 884 receives the lower part of the can entering the transfer turret.

35 The body member 878 is also provided with a lower flange 885 which rests upon and is supported by a lower sleeve 886 (Figs. 3, 4 and 45) also mounted on the column 865, a bushing 887 being interposed between the wall of the column 40 and the sleeve. The lower end of this sleeve 886 rests upon a washer 888 carried by the flange 866 of the column, and this sleeve, with sleeve 868, revolves around the column and imparts the proper rotation to the transfer turret 842.

45 The sleeve 886 adjacent its upper end and on one side only is extended outwardly in a boss section 889 which is formed interiorly with an opening in which is disposed part of an adjusting device for changing the relative vertical position between the ring members 872, 883, that is, the upper and lower sections of the transfer turret. This alteration of vertical height is effected by a raising or lowering of the sleeve 868 within the body 878 as will now be described.

50 The adjusting feature mentioned, comprises a pin 891 which is journaled for rotation within the boss section 889, the latter being cut away in its middle section to provide a chamber 892 in which the central part of the pin, provided 60 with worm teeth 893, is located. The pin 891 is formed with a square head 894 to which a suitable wrench may be applied for turning. The teeth 893 of the pin engage the teeth of a ring gear 895 which circles the sleeve 868 and the 65 column 865 being located directly beneath the lower end of the sleeve 886.

55 This ring gear rests upon the upper end of the sleeve 886 and its inner surface is provided with a fine pitch thread which cooperates as at 896 70 with a similar thread formed on the lower end of the sleeve 868. Rotation of the ring gear 895 on the sleeve causes the latter to raise and lower according to the direction of rotation. The sleeve 886 near its top and just beneath the 75

Can and cover seaming

chamber 892, is suitably grooved at 897 (Fig. 4) to provide a rotating fit on the upper end of a circular wall 898 formed in the intermediate ring 57.

5 When the can leaves the bottom plate 477 of the valve 475 and passes out of the valve pocket (station H, Fig. 16), it moves onto and is supported by a lower guide rail 899 (Figs. 4 and 39). This rail is circular in form, is located below the 10 ring plate 883 of the transfer turret and extends partially around the turret on one side. It is provided with a wall 900 which acts as a guide for the can and holds it within the transfer turret pocket 841 during its movement with the 15 turret. Guide rail 899 is carried upon and supported by a bracket 901 mounted upon a flange of the chamber housing 61 and by a bracket 902 mounted upon the upper wall of the ring section 57.

20 A cover guide rail is located above the transfer turret being substantially coextensive with the guide rail 899. This cover guide rail comprises segmental plates 903 supported upon arms of a spider frame 904 to which they are secured by suitable bolts.

25 The spider frame 904 (Fig. 6) is formed with a central half-cylindrical shell part 905 which fits around one side of the upper end of the column 865 and is clamped in place on the column by engagement with a corresponding half-cylindrical shell part 906 fitting around the other side of the column. These members 905, 906 are formed with projecting ears or lugs which are joined by bolts 907 which have elongated heads, as illustrated in Fig. 6. The spider frame in its clamped 30 position on the column is prevented from turning by a feather 908. At the lower end of the two mating parts 905, 906 an inturned annular flange 909 provides a rotatable connection with the upper end of the sleeve 868 and when the latter is raised and lowered for adjustment of can height, as previously described, this connection effects 35 a corresponding raising and lowering of the shell parts and the spider arms and guide plates carried thereby.

40 The transfer turret 842 is continually rotated by a gear connection with the main shaft 195. For this purpose a gear 911 (Figs. 4 and 7) is secured to the lower end of the sleeve 868 and moves over the column flange 866 and within a 45 chamber formed by a cylindrical housing 912 which is an integral part of the intermediate frame 57. The gear 911 meshes with a pinion 913 formed as an integral part of a vertically extending shaft 914 (see also Fig. 46) which is journaled in bearings 915 carried by the lower casing 52. This shaft 914 at its lower end carries a gear 916 (see also Fig. 8) which meshes 50 with and receives rotation from the gear 469 carried with the main shaft 195.

55 The shell part 903 (Fig. 6) is formed with an arm 917 which supports one side of a semi-circular splash plate 918 located in the vacuum chamber. This splash plate partially encircles the seaming head mechanism being positioned just outside of the path of travel of the rotating seaming heads. The other end of the splash plate is carried by one of the arms of the spider frame 904. This splash plate, as its name implies, stops any splash from the can as the can and cover are brought together in the seaming head and prevents juices, brine, etc. from flying over adjacent machine parts within the 60 vacuum chamber.

5 From a pocket 841 of the transfer turret 842, a can and cover are brought into the pocket of the seaming turret. This transfer is made when the turret pocket 841 registers with one of four pockets in the seaming turret at station I (Fig. 6). Upon entering the seaming turret pocket the can moves upon a plunger unit 919 (Fig. 3) of the seaming turret, this turret being 10 designated generally by the numeral 921. The seaming turret 921 is carried upon a gear 922 to which it is bolted. Gear and turret are mounted in bearings 923, 924 carried in the casing 52.

15 The gear 922 meshes with the gear 911 from which it receives continuous rotation which carries the seaming turret with its plunger units 919 in a circular path of travel during the time the cover and can are assembled and double seamed. The operation of assembly is effected 20 by a lifting of the plunger unit which inserts the can and cover into the seaming mechanism.

25 Each plunger 919 is lifted by a cam roller 925, rotatably carried on the end of the plunger unit riding over the raised section of a circular cam track 926 which is mounted upon a stationary cam body 927 resting upon the lower casing 52. A smaller cam roller 928 is also carried by each plunger unit inside of but adjacent the roller 925 and the smaller roller cooperates with a 30 cam track 929 formed in the cam body 927. The track 929 acting upon the roller 928 keeps the cam roller 925 upon its track 926. The cam roller 928 also provides a positive lowering action 35 for the plunger unit. A yielding spring device, designated generally by the numeral 931 is preferably embodied in each plunger unit 919 for a purpose hereinafter described.

40 A vertically disposed seaming shaft 932 is located centrally of the seaming turret 921 and rotates inside of the hub of the gear 922. The lower end of this shaft carries a sleeve 933 which is journaled in bearings 934 located below the bearings 923 and also carried by the casing 52. 45 This shaft 932 extends upwardly through an adjusting sleeve 935 rotatably mounted within an upwardly extending outer sleeve 936 of the turret 921. The seaming head and all parts associated therewith are carried upon the sleeve 935 which is tightly clamped with the outer sleeve 936 during the operation of the apparatus but which may be rotated within the outer sleeve 936 when raising or lowering the seaming head frame.

55 To rotate the sleeve 935 for such adjustment 3 a worm and worm gear device is used (Figs. 3 and 43). A worm thread 937 is formed on the peripheral edge of a flanged lower end of the sleeve and this thread is engaged by a worm thread 938 formed on an adjusting pin 939 rotatably mounted in a horizontal bore 941 formed in the seaming turret 921. A head 942 is formed on one end of the pin 939 and permits engagement by a socket wrench or other suitable tool 60 for rotating the pin and through the threaded connections 937, 938 also the sleeve 935.

65 The seaming head frame which carries the seaming mechanism and which is raised and lowered by the adjusting device, just described, 70 comprises a frame, designated generally by the numeral 945 (Fig. 2). This frame is formed with a depending stem 946 (see also Fig. 3) which extends outside of the sleeve part 936 of the seaming turret 921 and the stem is interiorly thread- 75

ed at 947, these threads engaging an outer thread 948 formed on the upper end of the sleeve 935.

Rotation of the sleeve 935 within the sleeve 936 in one direction causes the stem 946 of the 5 seaming head frame to move downwardly and a reversed movement lifts the seaming head frame and all parts carried thereby. A feathered connection 949 is formed between the parts 946, 936 which telescope one within the other and 10 this prevents relative rotation between the seaming head 953 and the seaming turret 921. In adjusted position these parts are securely locked together by a clamping bolt 951 (see Fig. 44) which forces wedges 952, sliding within the lower 15 end of the stem 946 to tightly engage the outer periphery of the turret sleeve 936.

Any suitable seaming head may be used within the seaming chamber, there being disclosed in the drawings a four-unit seaming head, designated generally by the numeral 953. This seaming head rotates on the central shaft 932 as an axis, the shaft being rotated in proper synchronism but at a different rate of rotation from the seaming head and by means of a planetary gear 20 unit, designated generally by the numeral 954, seaming rollers 955 associated with a seaming chuck 956 are caused to move in and out in proper time to effect the double seaming of the cover upon the can. The shaft 932 at its upper 25 end is journaled in bearings 957 carried by the chamber cover 62.

During the rotation of the seaming head, the usual or other suitable knockout rods are carried by the seaming head in a circular path of travel 30 and this movement causes a roller carried by each knockout unit to traverse the groove of a stationary cam 958 which is mounted on a cylindrical stationary support 959 bolted to and depending from the cover member 62. This cam 958 35 also carries a block 961 which is bolted to its bottom surface and which projects into the upper end of the seaming head and in turn carries bearing units 962 which rotatably and more rigidly support a part of the seaming head. This cam 40 958, the block 961 and the seaming head 953 are moved up and down with the adjustment of the stem 946 relative to the seaming turret. During such adjustment the cam 958 slides vertically upon the member 959 and is prevented from 45 rotating by means of a feather and featherway connection formed in these members, as illustrated in Fig. 2.

The seaming head frame 945 also carries a can pocket turret 963 which is formed with peripheral 50 can receiving pockets 964, there being a pocket arranged in axial alignment with each plunger unit 919. These pockets 964 cooperate with their plungers 919 and guide and hold the can cover for proper seaming position. The turret 963 is 55 prevented from turning on the stem 946 of the frame 945 by a key 960 (Figs. 2 and 44) secured to the stem and resting within a slot formed in the turret.

The sleeve 933 at its lower end supports a gear 60 965 (Figs. 3 and 8) which meshes with the gear 916 from which it receives driving rotation. It is in this manner that rotation of the shaft 932 is effected and through the planetary gear unit 954 the necessary movements of the seaming 65 rollers 955 are obtained. Such operations are well known in the art and it is believed that the brief and rather skeletonized description just given will be sufficient for present purposes.

The can, following the completion of the seaming operation, and after its removal from the

chuck 956 and its return to lower position with the plunger unit 919, is removed from the seaming head. It is from position J (Figs. 6 and 39) that such removal begins. The can is engaged by arms of a double, four-arm starwheel 966 which 5 sweep it from the plunger 919 and onto a guide rail 967 (Figs. 38 and 39) carried upon brackets 968 bolted to and resting upon the intermediate frame 57. This guide rail 967 is formed with side walls 969, which guide it in a circular path of 10 travel and lead it into the discharge valve at station K (Fig. 39).

During this travel in the starwheel 966, the can moves beneath a guide plate 971 (Figs. 6 and 38) secured on one side to one of the top 15 guide rail segments 903. The starwheel 966 is centralized on a reduced upper end 972 of a shaft 973 and this upper end provides a bearing 974 for the opposite side of the guide plate 971. The shaft 973 is formed with a flange 975 which supports the starwheel 966, the latter being bolted to the flange of the shaft. The shaft 973 is mounted for rotation in bearings 976 carried by a tubular extension 977 formed in the upper wall of the frame section 57. The starwheel 966, together with its shaft 973 is continually rotated through the medium of a gear 978 (see also Fig. 7) which meshes with and receives rotation from the gear 922.

Exit valve mechanism

30

The exit valve is similar in construction and operation to the entrance valve 475 although it is smaller in diameter and contains four pockets instead of the six pockets 476 of the other valve. 35 It is also associated with a float valve device identical in construction to the float valve 501 of the entrance valve unit.

The exit valve comprises a valve body 979 (Figs. 38, 39 and 40) formed as a hollow cylinder with 40 four spaced can receiving pockets 980. The valve body 979 is bolted to a bottom plate 981, which provides a floor for the support of cans inserted into the valve pockets, and is mounted upon a vertical shaft 982. This shaft is carried in a 45 swinging valve frame 983 formed as an open rectangular frame with spaced vertically extending members 984, 985. The frame part 985 is pivoted on a vertical shaft 986 which is supported by lugs 987 extending outwardly from a 50 bracket 988 bolted to the face of the chamber housing 61. Shaft 986 provides the pintle of a hinge connection for the swinging frame 983 which carries not only the entrance valve but also 55 a discharge starwheel.

The central valve shaft 982 is journaled in a bearing 989 carried in the upper part of the frame 983 and held in position by a cap 990 secured to the frame. The shaft 982 at its lower end is keyed to the hub 991 of a gear 992. This hub 991 60 is bolted to the bottom plate 981. The shaft 982 at its lower end is indirectly journaled in a bearing 993 which is mounted on the lower end of the gear hub 991, this bearing being carried in the frame 983.

A block 994 (Figs. 38 and 40) is secured to the lower end of the frame 983 below the end of the shaft 982 and carries a roller 995 which is supported upon a track formed by a circular flange 996 formed as an extension 997 of a frame part. 70 This provides anti-frictional support for the exit valve and for all of the parts carried by the swinging valve frame 983 and permits easy hinging of the frame part upon the shaft 986.

The section 984 (Figs. 39 and 40) of the swing- 75

ing frame 983 is provided with slots 998 in which clamping eye bolts 999 are adapted to be positioned to permit locking action of hand nuts 1000 threaded on the ends of the bolts. Each clamping bolt is pivoted at 1001 (Fig. 6) upon lugs 1002 formed in the bracket 315. This provides a locking device which is of the same description and which functions in the same manner as the clamping devices 334, 335 of the entrance valve 10 previously described.

The exit valve 979 provides an air-tight closure for the opening 132 in the vacuum chamber 71 and constantly rotates to receive seamed cans from the starwheel 966 and move them out of the vacuum chamber without any substantial loss of vacuum. To effect the necessary seal between the moving cylindrical wall of the valve and the wall of the chamber housing 61, a flexible or float valve seat is provided which is of similar construction but smaller than the float valve seat 501 at the entrance end of the chamber.

This float valve seat member comprises a frame 1005 (Figs. 38, 39 and 40) which embodies spaced top and bottom walls 1006, 1007 which are outside of the housing 61 and these walls merge into a cylindrical wall 1008. A central section of this cylindrical wall partially encircles the periphery of the exit valve throughout substantially half of its extent and engages with the peripheral walls of the valve body 979. This is only a yielding engagement, however, the frame 1005 being formed with a channel 1009 adjacent its inner face in which is disposed a flexible tube 1010.

This tube is confined on three sides by the channel walls and its fourth side or face engages the outer wall of the chamber housing 61 in a band of contact surrounding the opening 132. This tube 1010 like the tube 507 is adapted to be filled with air at a suitable pressure to hold the valve for easy turning while preventing leakage of air around the engaged surfaces. A valve stem and air valve 1011 (Fig. 38) permits filling of the tube.

The exit valve like the entrance valve has associated with it a hinged valve cover leaf 1012 (Figs. 39 and 40) which also closely engages the peripheral cylindrical wall of the valve and also acts in a combined lubricating and valve cleaning capacity. This valve cover leaf is considerably smaller than its companion leaf 523 inasmuch as the cans passing through the exit valve are all completely sealed and there is not the same danger of accumulation of dirt, juices and the like, on the valve faces.

The valve cover leaf 1012 is hinged at 1013 to lugs 1014 formed on the section 984 of the swinging valve frame 983 and is formed with an inside engaging surface 1015 at the extreme outer edge of the leaf which is grooved. This grooved surface communicates with the interior of a cup 1016 threadedly mounted on the top of the valve leaf. Cup 1016 is adapted to receive a drop of water at frequent intervals which passes through the cup and grooved surface 1015 and spreads over the periphery of the valve 979. This moisture will dissolve any foreign matter and clean the valve. A pipe 1017 having a discharge end positioned directly over the open end of the cup 1016 supplies the required moisture.

The oiling device of the valve cover leaf functions similarly to the oiling device of the companion valve leaf 523. In the present instance a groove 1018 extends vertically, being cut in the inner face of the valve cover leaf for the reception of a felt wick 1019 which projects slightly beyond the inner face of the leaf and engages the outer

periphery of the valve body 979. Oil may be supplied to the felt wick from an oil cup 1021 mounted on top of the valve leaf, its interior communicating with the upper part of the groove so that the oil flows by gravity into the wick.

The valve cover leaf 1012 is yieldingly held, during the operation of the machine, against the frictional surface of the valve 979 by a spring 1022 interposed between the leaf and one of the lugs 1014. This construction permits hinging back 10 of the valve leaf on its pivot 1013 to entirely clear the valve when access to its inner face is desired.

As a seamed can is moved into a pocket 980 of the valve 979 by the starwheel 966, it passes from the supporting floor of the guide rail 967 and slides 15 on to the bottom plate 981 of the valve (see Figs. 38 and 39) where it is engaged by a pair of spaced blocks in the valve pocket which center the can so that it is a sufficient distance from the peripheral edge of the valve to prevent striking of its outer 20 edge against the inner surfaces of the wall part 1008 of the float valve seat. Each pocket 980 contains an upper block 1025 which is secured by a bolt 1026 and nut 1027 into the upper horizontal wall of the valve body 979. Each upper block 25 1025 is slotted in a horizontal plane as at 1028 and is recessed at 1029 to provide a pocket for the can.

A lower block 1031 is also positioned in each 30 turret pocket 980, this block being substantially of the same shape as the upper block 1025. Each block 1031 is secured by bolts 1032 into the central part of the valve body 979 and is spaced above the floor 981 of the valve. The block 1031 is formed with a recess 1033 which is of the 35 same shape as the upper recess 1029, the walls of these aligned recesses engaging the body of the can and holding it within the valve against the action of centrifugal forces caused by the valve rotation so that the can will not engage 40 the wall 1008 of the float valve as previously described.

The parts 485, 486 of the entrance valve 475 may be shaped like the blocks 1025, 1031 if it is desirable to hold the open cans inwardly within 45 the valve pocket and against the centrifugal forces of the rotating entrance valve.

The exit valve is continually rotated in proper synchronization with the other operating parts of the machine and reference should now be had to Figs. 7, 38 and 41 which illustrates the train of gears and shafts used for driving the valve. The gear 992 is driven by connection with a pinion 1035 which is mounted upon the upper end of a vertical shaft 1036 journaled in an upper bearing 1037 carried in the upper end of a gear housing 1038 which is bolted to one end of the auxiliary casing 438. A cap 1039 is used to hold this bearing 1037 in proper position.

The lower end of the shaft 1036 is journaled 60 in a bearing 1041 which is also carried in the frame part 1038 and is held in position by a cap 1042. A bevel gear 1043 is loosely mounted on the shaft 1036 which at its lower end is reduced in diameter to provide for a thrust bearing 65 1044 shouldered on the shaft and resting upon the upper end of the bevel gear.

Gear 1043 is provided with one element of a mechanical slip clutch which is used to normally connect it with its shaft but which will operate 70 to disengage the gear from the shaft in the event of jamming or other abnormal conditions tending to prevent free turning of the shaft. For this purpose the gear 1043 carries a clutch plate 1045 having in its lower face one or more ball 75

seats in which one or more clutch balls 1046 are adapted to rest.

The clutch ball 1046 is carried in a disc 1047 which is located in face to face contact with the plate 1045 and is normally held upwardly against the latter by a spring 1048. This spring surrounds the lower end of the shaft 1036 and a stem formed on the disc 1047 and engages a washer 1049 mounted on the stem which backs up the ball 1046. The lower end of the spring rests against an adjusting nut 1050 threadedly engaging the lower end of the shaft 1036. In the event that abnormal conditions block the free rotation of the shaft 1036 the ball 1046 is forced 10 out of its seat and the gear 1043 then moves freely upon the shaft.

Gear 1043 meshes with a gear 1055 secured upon one end of a horizontal shaft 1056. The gear 1055 is formed with an elongated hub 1057 20 which supports that end of the shaft in rotating position within bearings 1058 carried in a bearing unit 1059 bolted to the frame part 1038. This bearing unit is located adjacent the connection between the frame part 1038 and the auxiliary 25 casing 438.

The opposite end of the shaft 1056 is similarly carried in a second bearing. A gear 1061 is secured to the end of the shaft and a hub of the gear supports a bearing unit 1062 which is held 30 in a projection 1063 formed in the casing 436. The gear 1061 meshes with a gear 1064 which is secured to the lower end of the shaft 462 and it is from this shaft that the exit valve receives its rotation.

35 Seamed can discharge

The seamed can after being carried through substantially 180° by the exit valve is ejected from the turret pocket 980. Fingers similar to the fingers of the entrance valve are used for this 40 purpose. A pair of fingers are located within each valve pocket and each pair comprises an upper finger 1071 (Figs. 38, 39 and 40) and a lower finger 1072 having the same shape and size and being vertically in alignment. Both fingers are 45 located upon a horizontal shaft 1073 with which they are secured by means of a feather 1074.

Upper finger 1071 moves within the horizontal slot 1028 of the upper block 1025 and lower finger 1072 moves beneath the lower block 1031. When 50 the can is received within a turret pocket at the station K (Fig. 39) the two fingers appertaining to that pocket are in retracted position and when it is discharged from the turret at position L, these fingers are in extended position being the 55 operating force that ejects the can.

Each shaft 1073 is journaled in an upper bearing 1075 formed in the upper wall of the valve body 979 and in a bearing 1076 formed in the lower floor plate 981. The movement of the 60 fingers just described is effected by oscillation of their shaft 1073 and for this purpose each shaft carries an arm 1076 on which is rotatably mounted a cam roller 1077 which, during the rotation of the valve, traverses a cam groove 65 1078 formed in a face cam 1079 mounted on the shaft 982 and bolted at 1081 to the swinging frame 983 adjacent the top bearing 989. A spacing collar 1082 is preferably interposed between the frame and the cam.

The discharge of the can from the exit valve begins prior to it reaching the position L (Fig. 39) and to permit this ejection and direct the can properly a casing 1083 (Figs. 1 and 39) extends forward from the outer edge of the float

valve wall 1008. This casing 1083 is formed by several wall sections 1084 (see also Fig. 6) which are located in front of the valve and enclose a discharge starwheel 1085 (Fig. 38). The wall sections 1084 are supported upon a plate 1086 which rests upon and is bolted to a hollow post 1087 formed as an integral part of a housing 1088 secured by bolts 1089 to the swinging valve frame 983. A floor segment 1091 is an integral part of the plate 1086 and extends beneath the first wall section 1084. It provides a supporting floor for the can during its passage from the valve pocket 980 into the starwheel 1085.

A casing cover 1092 (Fig. 38) is carried by the frame 983 and encloses the gear 992, this housing 15 being joined directly with the housing 1088 along one side and extending into and under a part of the frame 57 on the other side.

The starwheel 1085 comprises an upper member 1093 and a lower member 1094 both mounted 20 upon the upper end of a vertical shaft 1095. Each of these members is shaped to provide the four arms of the starwheel and both are secured in adjusted position upon the shaft. A feather inserted in one side of the shaft prevents rotation between the starwheel and shaft while permitting sliding movement. The lower member 1094 carries a supporting plate 1096 which is secured to its underface and this plate provides 25 a floor for the can during its travel with the 30 starwheel.

A guide rail 1097 (Figs. 6 and 39) is extended from the first wall section 1084 and this properly guides the can into the fingers of the starwheel 1085. Between the edges of two of the wall units 35 1084 there is formed a discharge opening 1098 and when the can reaches a point of discharge (indicated by M, Fig. 6), a guide rail 1099 projecting inwardly from one of the wall sections 40 engages the can and directs it out through the opening 1098. The opposite wall unit 1084 adjacent the discharge opening extends outwardly at 1100 and cooperates with the guide rail 1099 to form a discharge chute.

The shaft 1095 is journaled in an upper bearing 1101 which is seated within the upper end of the post 1087 and a similar bearing 1102 provides the necessary support for the shaft at its lower end. The bearing unit 1102 is enclosed by a cap 1103 bolted to the housing 1088. A gear 1104 (Figs. 7 and 38) is keyed to the lower end 50 of the shaft 1095 and meshes with the exit valve gear 992 from which it receives rotation for the starwheel 1085.

A brief reference has previously been made to 55 a drainage system by which any liquid which may be spilled from the cans during their travel through the vacuum chamber 71 is collected and discharged without breaking or interrupting the vacuum. The cans as they pass from unit to unit within the vacuum chamber are conveyed in as even and uninterrupted a manner as possible to prevent spilling and ordinarily very little liquid is spilled, but upon occasion spilling may 60 take place and it is highly desirable to provide for its removal. The various frame parts forming the floor of the vacuum chamber are accordingly so shaped as to collect and direct extraneous liquid to a common point of discharge.

The upper wall of the ring section 57 forms the 70 bottom of the vacuum chamber 71 and around the seaming turret 921 and the transfer turret 842, this frame section is outlined with an annular gutter 1111 (Figs. 3 and 4). On the one side 75

of the vacuum chamber adjacent the entrance valve, a lower overhang section 1112 of the chamber housing 61 is inclined to discharge into the gutter 1111. This gutter drains onto an inclined floor 1113 (Fig. 7) which spills into a sump 1114 which is located in one corner and near the bottom part of the frame 57.

A collecting drain cup 1115 (Figs. 1 and 7) joins with the sump and is bolted to the side of the frame 57 and discharges into a drain pipe 1116 which leads into a drain valve unit 1117 (see also Figs. 8, 14 and 15) which is bolted to the frame casing 438. This valve unit encloses a cylindrical chamber 1118, the interior of the pipe 1116 communicating with it and any liquid passing through the pipe is discharged into one of three pockets 1119 formed in a rotating valve member 1120 located in the casing of the valve unit. A cap 1121 is threadedly secured to this casing and forms a closure for the chamber on the front.

The valve member 1120 is keyed upon the end of a horizontally disposed shaft 1122 which is journaled for rotation within bearings 1123 formed in the casing of the valve unit. This shaft 1122 (see also Fig. 41) extends into the interior of the casing 438 and carries a spiral gear 1124 which meshes with spiral threads 1125 formed on the shaft 1056. The chamber 1118 is provided with a discharge opening 1126 to atmosphere which the valve member 1120 seals from the vacuum in the pipe 1116 while it discharges a pocket of liquid through the discharge opening.

35 Provision is also made for collection of lubricating oil draining from that part of the machinery below the vacuum chamber. Unlike the drainage for juices just described the oil drain is not under vacuum and a mere gravity discharge is made on to the section 54 of the base 51. Oil dripping from the parts below the floor of the frame 57 drains into an oil pan 1127 (Fig. 3) bolted to the bottom of the lower casing 52. 40 A discharge pipe 1128 leads from the low point of this pan with which it is threadedly engaged and discharges through a sieve head 1129 (see also Fig. 4) mounted on the end of the pipe. Oil issuing from this head is discharged on the wall 54 of the base over which it runs to a low point being confined within the rim 53 of the base.

Electric stop control devices

The electrical stop control devices for preventing injury to various parts of the machine in the event of jams or other abnormal operating conditions will now be described; first, in connection with the wiring diagram, (Fig. 47) and later in more detail in connection with the individual devices. All of the electrical circuits connected with these various stop devices, (each of which is a switch carried in a suitable housing) with one exception are wired in series with the motor wiring so that a breaking of the circuit at any switch point will interrupt the flow of electrical energy to the motor and cause the apparatus to stop. The exceptional stop device is only used when adjusting the machine without vacuum.

70 The electric motor 141 (Fig. 47) is preferably connected in a three phase electrical system comprising lead wires *a*, *b*, and *c* which preferably pass through a suitable service switch 50 and thence into the switch box 241. This switch box contains the start and stop buttons 242,

243 previously referred to but in the wiring diagram some of these elements have been spread out for the sake of clearness. A wire *d* leads from one side of the starting button switch 242 and connects with the wire *c*, the opposite side 5 of the switch being connected by a wire *e* to an automatic four contact switch *f*, one point of which is joined by a wire *g* to the motor 141.

An electromagnet 100 is carried in the switch box 241 and is associated by a movable solenoid core or similar device with the automatic switch embodying the contact points *f*. This switch is a spring-back or normally open switch. The magnet is joined by a wire *h* to the wire *b* and by a wire *i*, passing into the first contact post 15 unit 150 located with other such units in a terminal box 1131 (see also Fig. 1) mounted on the side of the housing 61. A wire *j*, leading from this contact unit passes into the first (as to sequence in the wiring circuit) of the electric 20 stop devices.

This stop device, designated by the numeral 1132, relates to a discharge drive slip clutch (see Fig. 42) and is mounted on a cap 1133 bolted to the side of the housing 1038. The opposite 25 side of switch 1132 is connected by a wire *k* to a second contact post unit 200 in the terminal box 1131. The opposite side of this contact post is joined by a wire *l* to a stop device 1135, this being the second device in sequence and it relates to the intake valve drive slip clutch. This 30 switch device (Figs. 18 and 41) is mounted upon a bracket 1136 bolted to the side of the casing 436.

The opposite side of switch 1135 is joined by 35 a wire *m* to a contact post unit 250 from which a wire *n* leads to an electric stop device 1137 which is associated with a low stack cover detector. This switch device is mounted upon a bracket 1138 (Fig. 22) bolted to one side of the 40 end feed post 595. A wire *o* connects the opposite side of switch 1137 with a contact post unit 300 and a wire *p* leads from there to another contact post unit 350. From this unit a wire *q* leads into the fourth electric stop device which 45 is numbered 1141 and is associated with a low vacuum switch (Figs. 1, 10 and 13) mounted on the lower end of the sleeve 274.

A wire *r* joins the opposite side of switch 1141 with a contact post unit 400 from which a wire *s* leads into an electric stop device 1142 which is associated with a main drive slip clutch and which is mounted upon an extension 1143 (Fig. 10) of the tubular member 184. A return wire *t* leads from the opposite side of switch 1142 55 into a contact post unit 450 from which a wire *u* joins with one side of the stop button switch 243. The opposite side of switch 243 is joined to the wire *e*.

When the electromagnet 100 is deenergized 60 the automatic switch is open at the contact points *f* and no energy is flowing into the motor 141 and the apparatus is idle. The start button switch 242 is normally open and if the machine is to be operated the button must first be 65 depressed. The stop button switch 243 is closed at all times excepting when its button is depressed.

In starting the motor with all electric stop devices cleared the service switch 50 is first 70 closed in the lead lines *a*, *b*, and *c*, and then the start button is depressed. A momentary starting current flows from the line *c*, wire *d*, switch 242, switch 243, wire *u* and through all of the contact posts within the terminal box 1131 pass- 75

ing through the various stop control switches 1142, 1141, 1137, 1135, 1132 in order, and thence through wire *i* and the electromagnet 100 and wire *h* back to the lead line *b*.

- 5 This energizes the electromagnet 100 and closes the automatic switch at contacts *f*, leading the current into the electric motor 141, the current passing through wire *c* and wire *g* and through the wires *a*, *b* and wires *v*, *w*, to excite 10 the fields of the motor and cause its rotation. As soon as the automatic switch is closed at the contact points *f*, a holding current is established which follows the same path as the starting current only now it passes along the wire *e* instead 15 of the wire *d*. The start button switch 242 no longer is included and its immediate release by the operator in no way affects the operation of the motor. As long as the current flows in this manner the motor operates, the electromagnet 20 100 remaining energized and holding the automatic switch closed and connecting the wires *a*, *b*, *c* with the wires *g*, *v*, *w* leading into the motor.

Since all of the stop control switches and the 25 stop button 243 are in electrical series, opening of the circuit at any of these points will automatically interrupt the current flowing through the electromagnet 100. The automatic switch connected therewith will immediately open and 30 remain open until the stop device has been restored to normal condition and the machine again started by operation of the start button 242. This insures the machine against damage by requiring the various switches to be cleared of 35 any obstruction prior to again starting the machine. It also requires the operation of the start button which, it will be recalled, is only accessible when the load of the machine is off of the slip clutch 151.

- 40 It will be observed that one of the stop control devices, i. e., the low vacuum switch 1141 prevents operation of the apparatus until the proper amount of vacuum exists in the vacuum chamber 71. It is sometimes desirable in making 45 pairs and adjusting the various working parts of the machine to operate the apparatus under power without vacuum in the vacuum chamber. Provision is made to do this by cutting out the contact posts 300 and 350 as well as the vacuum 50 switch 1141. This is made possible by a manually operated control switch 1145 which is associated with the runway for the cans entering the timing disc. Switch 1145 (Figs. 5, 6 and 16) is mounted upon arms 1146 projecting outwardly 55 from the frame hood 302 and is operated in a manner which will be hereinafter fully described.

This switch 1145 (Fig. 47) is connected by a wire *x* to the wire *s* at contact post unit 400 and 60 a wire *y* connects the opposite side of switch 1145 with the wire *o* at contact post unit 300. When this switch 1145 is closed, the starting and holding currents flow as previously described on one side as far as the wire *s* and thence by wire 65 *x* through switch 1145, wire *y* and wire *o*, through switch 1137 and so on throughout the rest of the circuit. These circuits do not include the low vacuum switch 1141 which may be open by reason of there being no vacuum at the time 70 within the vacuum chamber 71.

The various contact post units 150, 200, 250, 300, 350, 400 and 450 are all located within the terminal box 1131 for a definite purpose. Each electrical stop device is connected between two 75 of the contacts and when flow of current through

the motor is interrupted the particular switch which has been opened as a result of undesirable conditions in the machine may be quickly determined by shorting across adjacent contacts until such shorting is found to indicate a circuit. The 5 switch or stop devices between such contacts is, of course, the one at which diverse conditions have caused circuit interruption.

This inspection of the terminal box and the shorting across between contact units may be 10 made in any one of several ways as by an electric light mounted with exposed wire ends which may be successively applied to adjacent contact units. An electric bell could be used instead of the light. One would give visual, the other 15 audible indication of completions of the circuit. There is not sufficient current flowing through such a light or bell to energize the motor and start the machine but is adequate to indicate an uninterrupted circuit. For example, assuming 20 the stop device 1132 is disconnected by adverse conditions, a testing light connected between the contact units 150, 200 would be illuminated indicating that all other stop devices were clear. Switch 1132, therefore, would be immediately 25 examined and the difficulty removed.

The mechanical details connected with the 30 operation of the various stop control devices will now be described and properly associated with the yielding parts which are affected by adverse operating conditions in the machine. These will be considered in the same order as before. The first of these is switch 1132 and reference should be had to Figs. 1 and 42.

This switch is normally closed and is opened 35 and the current broken at the switch only when a push button 1150 is depressed. Depression of the button depends upon movement of washer 1049 of the slip clutch on the shaft 1036. Operation of the clutch forces the washer downwardly 40 against the action of the spring 1048 when the clutch ball 1046 rides out of its seat in the plate 1045.

This movement oscillates a bell crank lever 1151 pivoted at 1152 to a lug 1153, projecting 45 inwardly from one wall of the cup member 1133. An arm 1154 of the bell crank lever projects beneath the washer 1049 and during depression of the washer the arm is engaged and moved. The resulting oscillation of the bell crank lever 50 moves an opposite arm 1155 of the lever toward the right (Fig. 42).

A setscrew 1156 is carried in the arm and this strikes against and depresses the button 1150 of the switch 1132. The button 1150 returns to its 55 normal position only when the obstruction is removed and when the slip clutch is again restored to normal. The spring pressed button 1150 restores the bell crank lever to the position 60 illustrated in Fig. 42, a second setscrew 1157, carried by the arm 1154, striking against the wall of the cup member 1133 and holding the parts in normal position with the arm 1154 just out of contact with the washer 1049.

The second stop device 1135 relates to the in- 65 take valve drive slip clutch and reference should now be had to Figs. 18 and 41. The slip clutch parts 445, 448 and 451 are directly involved. When the spring 452 yields to permit downward movement of the washer 451 a pin 1165 is moved. 70 This pin slides in a vertical bore cut through a wall of the casing 436 and when depressed engages and lowers an arm 1166 of a lever 1167 which oscillates on a pin 1168 carried in lugs 1169 formed in the bracket 1136. This raises the 75

opposite arm of the lever 1167 and causes a setscrew 1171 carried in the lever arm to engage and lift a spring pressed push button 1172 of the stop device 1135. This breaks the circuit and stops the machine.

5 The push button 1172 normally extends downwardly and after removal of the difficulty and restoration of the slip clutch it returns to normal (Fig. 41) resetting the lever 1167. A setscrew 10 1173 carried in the lever arm 1166 engages a part of the casing 436 and limits the return movement of the lever so that the upper end of the pin 1165 will not bind against the washer 451.

15 The next stop device 1137 is concerned with the minimum quantity of can covers 605 in the cover magazine. An inspecting device is used for automatically inspecting the stack of covers within the magazine at definite intervals of time. Normally the presence of at least a given number 20 of covers in the stack stops movement of part of the inspecting device and prevents breaking of the circuit at the switch 1137 but in the absence of covers the full movement of the inspecting element takes place and the switch is opened.

25 The period of cycle or time inspection intervals is once for the feeding of every fourth cover, which means the number of covers within the stack must be within four covers of a predetermined minimum. Reference should now be had 30 to Figs. 18, 22 and 27 which illustrate the details associated with the stop switch 1137.

35 The inspecting element which actively engages the edges of can covers 605 within the magazine 603 comprises an arm 1175 (Fig. 18) which is carried upon the upper end of a vertically extending shaft 1176 which is mounted for oscillation within the depending frame part 639. This arm moves in a horizontal plane which is slightly above the top of the magazine plate 601 and its inner or free end is adapted to engage the cover edges. When the stack of covers has been exhausted so that the top cover is beneath the plane of operation of the arm 1175 its outer end cannot engage a cover. At such a time there are 45 still substantially 18 or 19 covers left in the magazine which is the minimum of quantity to give the desired weight for the proper performance of the cover separating devices previously described.

50 A lever 1177 (Figs. 18 and 27) is secured to the lower end of the shaft 1176 and is formed with an enlarged body section 1178 which contains a spring barrel 1179 and a spring 1180. This spring urges the barrel 1179 outwardly where its 55 ends engages the frame part 639, this spring action tending to move the lever 1177 in a clockwise direction (Fig. 27). The free end of the lever 1177 carries a cam roller 1184 which under the action of the spring 1180 normally rests 60 against the periphery of a plate cam 1185 which rotates around the shaft 669 as an axis. This cam is caused to make one complete revolution for each fourth feeding and separating action of the feeding devices.

65 Cam 1185 is mounted upon the lower end of a sleeve 1186 (Fig. 22) which is enlarged at its upper end and formed with gear teeth 1187 (see also Fig. 27). This sleeve 1186 is loosely mounted on a lower reduced end 1188 of the shaft 669 and is contained within a gear box 1189 bolted to the under face of the bearing 671.

The gear teeth 1187 mesh with gear teeth 1191 formed in a double gear which is rotatably mounted on a stud 1192 secured into the gear box 1189.

70 75 The double gear 1191 is also formed with upper

and larger diameter gear teeth 1193 which mesh with and are driven by gear teeth 1194 formed in the upper part of the shaft section 1188.

Continual rotation of the shaft 669 by reason of this gear connection imparts a reduced speed of rotation to the cam 1185 and this gives the desired ratio of one to four between the testing and the separation of covers from the magazine. A second lever 1195 (see also Fig. 18) is mounted for slight vertical movement on a pivot pin 1196 10 secured to the enlarged part 1178 of the lever 1177. The two levers move as a unit in a horizontal plane which movement is controlled through lever 1177 and roller 1184 by the surface of the cam 1185. 15

The free end of the lever 1195 carries a cam roller 1197 which normally rests lightly upon the upper surface of a push button 1198 associated with the stop device switch 1137. This push button, like all of the push buttons of the electrical 20 stop devices previously described, is normally spring-held in raised position with the enclosed switch closed. When the supply of covers falls below the plane of movement of the arm 1181 the lever 1195 is caused to depress the button 1198 25 and to break the circuit.

The periphery of the cam 1185 throughout substantially three-fourths of its circumference is uniform and of a given diameter, as illustrated in Fig. 27, and as long as the roller 1184 rides on this surface, the levers 1177, 1195 and the shaft 1176 are held in a position so that the inspecting arm 1175 is just out of engagement with the outer edge of the stack of covers within the magazine. In the remaining quadrant of cam surface, 35 the periphery of the cam 1185 is reduced in diameter as at 1190. When this portion 1190 of the cam passes the roller 1184, the spring 1180 tends to keep the roller 1184 in engagement with the cam surface and levers 1177, 1195 and shaft 1176 40 move and the arm 1175 is brought toward the stack of covers within the magazine.

If the stack of covers is sufficient to extend in the path of movement of the arm 1175, the latter is blocked in its travel and the shaft 1176 is 45 prevented from further oscillation. The cam surface 1190 of the rotating cam 1185 now leaves the roller 1184 while the arm 1175 rests against the covers. After this section 1190 of the cam has passed the roller 1184, the larger diameter of 50 the cam re-engages the latter and moves the lever 1177 and associated parts back into position. This action takes place without any interruption of the current through the switch 1137.

In the event that the supply of covers within 55 the magazine is sufficiently exhausted to allow further movement inwardly of the arm 1175, the levers 1177 and 1195 continue their movement in a clockwise direction (Fig. 27) or toward the left (Fig. 22) so that the cam roller 1197 is 60 brought under a depending inclined cam surface 1199 (see also Fig. 18) formed adjacent the depression 1190 of the cam 1185. This depending cam surface forces the roller 1197 downwardly oscillating the lever 1195 on its pivot 1196 65 and depressing the push button 1198 of the stop device 1137. This immediately disconnects the circuit flowing through the switch and stops the operation of the machine.

The next electric stop device in the order of 70 position within the electrical circuit is the low vacuum switch 1141 illustrated in Figs. 10 and 13. This switch is provided with a spring-pressed push button 1201 which extends within the hollow shell 274 and is directly beneath the lower 75

end of the rod 275. An adjustable contact button 1202 is threadedly engaged to the rod and is held in adjusted position by a locknut 1203. Reference has already been made to the operation 5 of the sylphon bellows 271 and movement of the bellows imparts a corresponding movement to the rod 275 connected to its upper wall.

During the normal operation of the machine, when there is the proper amount of vacuum 10 within the vacuum chamber 71, the pressure of air on the inside of the sylphon bellows (atmosphere) is sufficient to hold it in its expanded position, as illustrated in Fig. 13, wherein the rod 275 is held in its raised position. This holding 15 of the sylphon parts by atmospheric pressure is also sufficient to overcome a spring 1204 which is located in the upper end of the housing 274, its lower end resting upon a washer 1205 held in fixed position on the rod by a nut 1206.

20 The expression "proper amount of vacuum" refers to a predetermined vacuum condition or gage point which is obtained at will by adjustment of the compression upon the spring 1204 by the location of the nut 1206.

25 When the vacuum within the chamber 71 has been sufficiently disturbed a counteracting pressure builds up against the outside upper end of the sylphon bellows 271 within the chamber 272 and this reduces the holding action of the atmosphere 30 so that the spring 1204 expands and depresses the rod 275. When this takes place the contact button 1202 moves against the push button 1201 of the switch 1141 and the current is accordingly broken at this position.

35 The electric stop device 1142 is associated with the main shaft 195 and is controlled by a drive slip clutch mounted upon the shaft and located within the tubular member 184, this being best illustrated in Figs. 2 and 10. In the preceding 40 description it was stated that the shaft 195 was driven by the gear 194 which was mounted upon its upper end. This gear is connected with the shaft through the medium of the slip clutch now to be described. In the event that the shaft is 45 blocked or prevented from rotating by abnormal operating conditions within the apparatus, the slip clutch allows the gear 194 to turn freely upon it.

For this purpose gear 194 is provided with a 50 sleeve section or hub 1211 which extends downwardly within the bearing units 196 previously described. The moving parts of these bearing units are held in fixed position relative to the sleeve hub by a locknut 1212 threadedly secured 55 thereon. The stationary parts of the bearing units are held in position by a flanged collar 1213 bolted to the lower end of the supporting cup 197.

60 The lower end of the gear hub 1211 supports a disc 1214 which is keyed in place and is held against vertical movement by a washer 1215 mounted on the hub. This disc 1214 constitutes one of the elements of the slip clutch, its lower face containing one or more pockets 1216 in which one or more clutch buttons 1217 normally rest. The clutch button is carried in a disc 1218 slideably mounted upon the shaft 195 with which it rotates through a feather connection 1219. This 65 clutch button 1217 is backed up by a washer 1221 which is held upwardly against the disc 1218 by a coil spring 1223 mounted upon the stem of the disc and surrounding the shaft 195. The lower end of this spring is engaged by an adjusting nut 1224 threadedly secured to the shaft.

A washer 1225 is held by bolts to the upper end of the shaft and its outer edge projects outwardly over the upper end of the gear hub 1211. This construction provides the slip connection between the gear 194 and the shaft 195, the clutch button 5 1217 when properly seated forming the holding element between these members. When the shaft 195 is blocked against normal rotation the clutch button 1217 is forced downwardly and out of its seat 1216 and the washer 1221 is thereupon moved 10 compressing the spring 1223 and allowing free movement of the gear 194 on the shaft 195. This slip movement is immediately accompanied by a breaking of the electric circuit at the stop device switch 1142.

15 A bell crank lever 1226 (Fig. 10) is pivoted at 1227 to the tubular member 184 and one arm of the lever carries a setscrew 1228 which rests against a spring-pressed push button 1229 of the stop switch 1142. This bell crank lever 1226 is 20 provided with an arm 1231 which extends below the outer edge of the washer 1221 and is normally held just out of engagement. This normal position is maintained by the spring-held push button 1229, a limit stop being obtained by engagement 25 of an extension 1232 of the bell crank lever against a setscrew 1233 held in a lug 1234 formed in the tubular member 184.

Depression of the washer 1221 is transmitted to the arm 1231 of the bell crank lever 1226 which 30 rocks on its pivot and forces the setscrew 1228 against the push button 1229 and moves it to interrupt the electric current passing through the switch 1142. After the obstruction has been removed and the clutch button 1217 and other parts 35 of the slip clutch again restored, the bell crank lever 1226 is automatically returned to normal position, the switch 1142 being again closed.

The last electric stop device 1145 to be described relates to the manual runway switch. 40 This device, unlike the stop devices just described, has a switch element which is open during the normal operations of the apparatus and which must be closed by hand. It has a double function, the first of which has been described in connection with the description of the wiring diagram, 45 that feature which permits operation of the machine under power even though there is no vacuum within the vacuum chamber by cutting out, electrically, operation of the low vacuum switch 50 1141.

A second function of the device is to automatically stop the machine during testing and adjusting should a can inadvertently be fed into the machine and along the regular entrance path. 55 This second feature prevents improper seaming of a can. Such inadvertent can feeding is probable following a repair or adjustment when the operator may start feeding of cans before the vacuum within the chamber has been properly 60 established.

Reference should now be had to Figs. 5, 6 and 16 wherein it will be observed that the manual runway switch 1145 is located adjacent the entrance A. During the normal operation of the machine, this switch is open and a spring-held 65 push button 1235 is in its outer or extended position. A hand lever 1236 is mounted upon the upper end of a vertical shaft 1237 which at such time is beneath the guide rail 375 (Fig. 16) and 70 out of the way of incoming cans fed at station A upon the disc ring 292.

The shaft 1237 is mounted for oscillation within a bearing 1238 (see also Fig. 5) carried in a bracket 1239 extending outwardly from the hood 75

frame 302. This bracket is located between the arms 1146. At its lower end the shaft 1237 carries a cam block 1241 which is located in horizontal alignment with the push button 1235 of switch 1145. During the normal operation of the machine, this cam block 1241 does not contact the push button 1235.

In order to operate the machine under power when there is no vacuum within the chamber 11, it is only necessary to move the arm 1236 from the position illustrated in full lines in Fig. 16 to that indicated by the broken lines. In this latter position the arm extends across the path of cans entering the machine at station A. The cam block 1241 now engages and depresses the push button 1235 and closes the switch at this point. These movable parts remain in this position as long as adjustments are being made to the machine and at such time the low vacuum switch 1141 does not function.

After adjustments have been completed the introduction of cans into the machine automatically throws out the arm 1236 releasing the push button 1235 and breaking the current passing through the switch 1145. If the vacuum chamber 11 is properly conditioned, that is vacuumized, the low vacuum switch 1141 functions to maintain a closed circuit through the electric motor 141 and the can passes through the machine in regular seaming operations. In the event of insufficient vacuum, the flow of electric current is interrupted at switch 1141 and the machine stops. Thus, the double function of the manual runway switch 1145 is exemplified.

It is thought that the invention and many of its attendant advantages will be understood from the foregoing description and it will be apparent that various changes may be made in the form, construction and arrangement of the parts, without departing from the spirit and scope of the invention or sacrificing all of its material advantages, the form hereinbefore described being merely a preferred embodiment thereof.

We claim:

1. In an apparatus for vacuumizing and sealing containers, the combination of a casing enclosing a vacuum chamber and having an opening in its wall, a can conveying valve adapted to rotate on a fixed vertical axis located outside of said casing said valve partially extending into said casing opening, and a float valve seat having a relatively flat section engaging the outside of said casing and having a cylindrical section extending through said opening and into said vacuum chamber and engaging that part of said conveyor valve which is within the vacuum chamber and providing a seal for the chamber at said opening and around said valve, said float valve seat being free of attachment to said casing and valve and freely movable in all directions relative thereto.

2. In an apparatus for vacuumizing and sealing containers, the combination of a casing enclosing a vacuum chamber and having an opening in its wall, a can conveying valve adapted to rotate on a fixed vertical axis located outside of said casing said valve partially extending into said casing opening, a float valve seat disposed between and free of attachment to said casing wall and said valve, said valve seat having a relatively flat section engaging the outside of said casing and having a cylindrical section extending through said opening and into said vacuum chamber and engaging that part of said conveyor valve which is within the vacuum chamber, and flexible means carried by said float valve seat

for sealing the connection between it and said casing and for maintaining the engagement between said cylindrical float valve seat section and said conveyor valve.

3. In an apparatus for vacuumizing and sealing containers, the combination of a casing enclosing a vacuum chamber and having can inlet and can outlet openings, a rotating entrance valve for introducing cans into said chamber and extending into said can inlet opening, said valve being mounted for bodily movement towards and away from said casing, a rotating exit valve for discharging cans from said chamber and extending into said can outlet opening, a float valve seat extending into said inlet opening and engaging said entrance valve and sealing the vacuum chamber at said inlet opening, a similar float valve seat extending into said outlet opening and engaging said exit valve and sealing the vacuum chamber at this opening, and means carried by said float valve seats for establishing the proper degree of pressure engagement with their respective rotating valves.

4. In an apparatus for vacuumizing and sealing containers, the combination of a casing enclosing a vacuum chamber and having openings in its wall, can conveying valves adapted to rotate on fixed vertical axes while extending into said casing openings, float valve seat members associated with said valves, each member having a flat section and a cylindrical section, the latter extending through a said casing opening and into said vacuum chamber and providing a valve seat for pressure engagement with a said valve, said float valve seat being free of attachment to said casing and valve and freely movable in all directions relative thereto, and yielding means interposed between the exterior wall of said casing and the flat sections of said float valve seat members for sealing the casing openings around said valves.

5. In an apparatus for sealing containers under vacuum, the combination of a casing having an opening and enclosing a vacuum chamber, a rotary valve closing said opening for introducing cans and covers into said vacuum chamber, can conveying mechanism for feeding cans into said valve, a cover magazine for holding can covers in stacked formation, cover separating devices for individually removing covers from the stack, means for feeding a separated can cover in a circular path of travel and into axial alignment with a fed can within said valve, a marking device located at a marking station adjacent the path of travel of said cover, means interposed in the path of travel of the cover for deflecting it into marking position at said marking station and for momentarily obstructing its movement while being operated upon by said marking device, and means for passing said marked cover under said obstructing means.

6. In an apparatus for sealing containers, the combination of can conveying mechanism for feeding cans to a seaming station, a vacuum chamber enclosing the seaming station, a cover magazine for holding can covers in stacked formation, cover separating devices including a rotating separating disc for individually removing covers from the stack, means including a rotating feeding disc for feeding a separated can cover into axial alignment with a can being fed to said seaming station, means in the vacuum chamber for assembling the can and cover ready to be united, means at said station for uniting can and cover, and devices associated with said cover sep-

arating disc for preventing separation of said cover from said stack when there is no can to receive it.

7. An apparatus for sealing containers, comprising in combination a cover magazine for holding can covers in stacked formation, means for feeding a can cover in a circular path of travel from said magazine, marking devices located at a marking station adjacent the path of travel of said cover, and means interposed in the path of travel of the cover for deflecting it outwardly into said marking station to momentarily release it from said cover feeding means and to arrest its travel during the operation of said marking devices, a vacuum chamber and cover seaming means therein, means for separately feeding cans and covers into said vacuum chamber, and means in the vacuum chamber for assembling the cans and covers ready to be seamed together.

8. In an apparatus for sealing containers under vacuum, the combination of a casing having an opening and enclosing a vacuum chamber, a rotary valve closing said opening for introducing cans and covers into said vacuum chamber, can conveying mechanism for feeding cans into said valve, a cover magazine for holding can covers in stacked formation, cover separating devices for individually removing covers from the stack, means including a rotating feeding disc for feeding a separated can cover by two stages in a circular path of travel and into axial alignment with a fed can within said valve, spaced devices at different levels carried by said disc for successively engaging the can cover in its stages of travel, and means for shifting the cover from one level to the other.

9. In an apparatus for sealing containers under vacuum, the combination of a casing having an opening and enclosing a vacuum chamber, a rotary valve closing said opening for introducing cans and covers into said vacuum chamber, can conveying mechanism for feeding cans into said valve, a cover magazine for holding can covers in stacked formation, cover separating devices for individually removing covers from the stack, means including a rotating feeding disc for feeding a separated can cover by two stages in a circular path of travel and into axial alignment with a fed can within said valve, spaced devices at different levels carried by said disc for successively engaging the can cover in its stages of travel, means interposed in the path of travel of the cover for deflecting it from engagement with the first of said spaced devices, and means for shifting the cover from one level to the other.

10. In an apparatus for sealing containers under vacuum, the combination of a casing having an opening and enclosing a vacuum chamber, a rotary valve closing said opening for introducing cans and covers into said vacuum chamber, can conveying mechanism for feeding cans into said valve, a cover magazine for holding can covers in stacked formation, cover separating devices for individually removing covers from the stack, means including a rotating feeding disc for feeding a separated can cover in a circular path of travel and into axial alignment with a fed can within said valve, actuating means for rotating said feeding disc, and means for adjusting the relative position between said feeding disc and said actuating means.

11. In an apparatus for sealing containers under vacuum, the combination of a casing having an opening and enclosing a vacuum chamber,

ber, a rotary valve closing said opening for introducing cans and covers into said vacuum chamber, can conveying mechanism for feeding cans into said valve, a cover magazine for holding can covers in stacked formation, cover separating devices for individually removing covers from the stack, a trip finger for normally supporting said stack of covers against separation, means actuated by a can in said can conveying mechanism for withdrawing said trip finger from stack supporting position to allow separation of a cover, and means for feeding the separated can cover into said valve and into axial alignment with the can.

12. In an apparatus for sealing containers under vacuum, the combination of a casing having an opening and enclosing a vacuum chamber, a rotary valve closing said opening for introducing cans and covers into said vacuum chamber and having pockets, can conveying mechanism for feeding cans into the pockets of said valve, a cover magazine for holding can covers in stacked formation, cover separating devices for individually removing covers from the stack, a trip finger for normally supporting said stack of covers against separation, means actuated by a can in said can conveying mechanism for withdrawing said trip finger from stack supporting position to allow separation of a cover, means for feeding the separated can cover into a pocket of said valve and into axial alignment with the can, and pocket members for holding the cover separated from the can during their travel in said valve pocket and during their introduction into said vacuum chamber.

13. In an apparatus for sealing containers, the combination of a seaming mechanism, can conveying mechanism for feeding a can into said seaming mechanism, a vacuum chamber enclosing said seaming mechanism, a cover magazine for holding can covers in stacked position, cover separating devices for individually removing covers from the stack, said devices comprising a rotating separator disc which supports the stack of covers on one side during a part of its rotation and which separates the lowermost cover in the stack along one side by moving it from horizontal into inclined position, and means for assembling each can and cover in said vacuum chamber ready for the operation of said seaming mechanism, and means for feeding the covers including a rotating feeding disc which engages said inclined separated cover and removes it from the magazine.

14. In an apparatus for sealing containers, the combination of a seaming mechanism, can conveying mechanism for feeding a can into said seaming mechanism, a vacuum chamber enclosing said seaming mechanism, a cover magazine for holding can covers in stacked position, cover separating devices for individually removing covers from the stack, said devices comprising a rotating separator disc which supports the stack of covers on one side during a part of its rotation and which separates the lowermost cover in the stack along one side by moving it from horizontal into inclined position, means for feeding a separated cover into said vacuum chamber and to a can and into said seaming mechanism, said feeding means including a rotating feeding disc which supports one side of said separated cover after it has been brought into inclined position, and a marking device for marking said separated cover while still supported by said feeding device, and means in said vacuum chamber for as-

sembling each can with its cover ready for the operation of the seaming mechanism.

15. In an apparatus for sealing containers, the combination of a seaming mechanism, can conveying mechanism for feeding a can into said seaming mechanism, a vacuum chamber enclosing said seaming mechanism, a cover magazine for holding can covers in stacked position, cover separating devices for individually removing covers from the stack, said devices comprising a rotating separator disc which supports the stack of covers on one side during a part of its rotation and which separates the lowermost cover in the stack along one side by moving it from horizontal into inclined position, means for feeding a separated cover to a can and into said seaming mechanism, said feeding means including a rotating feeding disc which supports the separated cover after it has been brought into inclined position while it removes said separated cover from the magazine, and a trip device actuated by a can while in said can conveying mechanism for insuring separation and feeding of a cover only when a can has been fed, said conveying and feeding mechanisms including means in said vacuum chamber for assembling the can and cover ready for the operation of said seaming mechanism.

16. In an apparatus for vacuumizing and sealing containers, the combination of a casing enclosing a vacuum chamber, a seaming mechanism in said chamber, can conveying mechanism for feeding a can into said vacuum chamber and into said seaming mechanism, a cover magazine located outside of said chamber for holding can covers in stacked position, cover separating devices for individually removing covers from the stack, said devices comprising a rotating separator disc which supports the stack of covers on one side during a part of its rotation and which separates the lowermost cover in the stack along one side by moving it from horizontal into inclined position, and means for feeding a separated cover into said vacuum chamber and in alignment with a can in said seaming mechanism, said feeding means including a rotating feeding disc which supports the side of said separated cover opposite to its separator disc support after it has been brought into inclined position and which then moves said separated cover into horizontal position while still supporting it along one side.

17. In an apparatus for sealing cans under vacuum, the combination of a casing having an opening in its wall and enclosing a vacuum chamber in which the cans are sealed, a rotating valve extending into said vacuum chamber through said opening for introducing cans and covers into said vacuum chamber, a valve frame hinged on said casing and rotatably supporting said valve, can conveying mechanism mounted on said valve frame for feeding cans into said valve, a cover magazine for holding can covers in stacked formation and carried by said valve frame, cover separating devices for individually removing covers from the stack and also carried by said valve frame, means also carried by said valve frame for feeding a separated can cover into said valve, and means for holding said valve frame in position against said casing to insure proper feeding of can and cover into said valve.

18. An apparatus for sealing cans under vacuum comprising in combination, a casing having an opening in its wall and enclosing a vacuum chamber in which cans and covers are sealed together, a rotating valve extending into said

chamber through said opening for introducing cans and covers into said chamber, a valve frame mounted on said casing and rotatably supporting said valve, can timing devices carried by said valve frame for placing a can into timed relation with the operations of the machine, can conveying mechanism mounted on said valve frame for feeding timed cans from said timing devices into said valve, a can cover magazine frame carried by said valve frame, cover feeding means mounted on said magazine frame for feeding cans into said valve, marking devices also mounted upon said magazine frame for impressing a mark in said cover prior to its reaching said valve, and means for adjusting the position of said magazine frame and all parts carried thereby relative to said valve frame.

19. An apparatus for sealing cans under vacuum comprising in combination, a casing having an opening in its wall and enclosing a vacuum chamber in which cans and covers are sealed together, a rotating valve for conveying cans through said opening and having can receiving pockets, said valve being mounted for bodily movement relative to said vacuum chamber, a float valve seat carried by said casing and having a cylindrical valve engaging surface, and means located in said valve pockets for holding the cans away from the cylindrical wall of said valve engaging surface during their travel with said valve, and means in said vacuum chamber for assembling separately introduced cans and covers so that they become ready for the seaming operation.

20. An apparatus for sealing cans under vacuum comprising in combination, a casing having an opening in its wall and enclosing a vacuum chamber in which cans and covers are sealed together, a rotating valve for conveying cans through said opening and having can receiving pockets, a float valve seat carried by said casing and having a cylindrical valve engaging surface, and can holders located in said valve pockets and shaped to receive cans fed into said valve and to hold them against centrifugal forces set up by said rotating valve so that they will not engage the cylindrical wall of said valve seat, and means in said vacuum chamber for assembling separately introduced cans and covers so that they become ready for the seaming operation.

21. In an apparatus for sealing containers under vacuum, the combination of a casing having an opening and enclosing a vacuum chamber, a rotary valve having can receiving pockets and closing said opening and for introducing cans into said vacuum chamber, said valve having means for holding the covers so as to leave the cans open, a float valve seat having a cylindrical valve engaging surface and engaging said valve, and means associated with said valve seat for progressively vacuumizing said valve pockets and the cans carried therein prior to the cans reaching said vacuum chamber.

22. In an apparatus for sealing containers under vacuum, the combination of a casing having an opening and enclosing a vacuum chamber, a rotary valve having can receiving pockets and closing said opening and for introducing cans into said vacuum chamber, said valve having means for holding the covers so as to leave the cans open, and a float valve seat having a cylindrical valve engaging surface extending through said opening and into said vacuum chamber and engaging said valve, said valve seat having openings which provide communication between a said valve pocket and said vacuum chamber and

effect a progressive vacuumization of said valve pockets and the cans carried therein prior to the cans reaching said vacuum chamber.

23. An apparatus for sealing cans under vacuum comprising in combination, a casing having an opening in its wall and enclosing a vacuum chamber in which cans and covers are seamed together, a rotating valve for conveying cans through said opening, a hinged valve cover leaf mounted adjacent to and having pressure engagement with said valve, and means for supplying a cleaning solvent to the valve engaging surfaces of said cover leaf and said valve.

24. An apparatus for sealing cans under vacuum comprising in combination, a casing having an opening in its wall and enclosing a vacuum chamber in which cans and covers are seamed together, a rotating valve for conveying cans through said opening, a hinged valve cover leaf mounted adjacent to and having pressure engagement with said valve, means for supplying a cleaning solvent to the valve engaging surfaces of said valve cover leaf and said valve, and wiping means for lubricating said valve and valve leaf surfaces.

25. In an apparatus for vacuumizing and sealing containers, the combination of a casing providing a vacuum chamber and having can inlet and can outlet openings communicating with said chamber, can conveying mechanism including rotating valve members extending into said openings for introducing cans into and for discharging cans from said chamber, and yielding means free from attachment to said chamber wall and said valves and arranged between said valve members and said casing for providing air-tight seals for said chamber openings.

26. An apparatus for sealing cans under vacuum comprising in combination, a casing having an opening in its wall and enclosing a vacuum chamber in which cans and covers are seamed together, a rotating valve for conveying cans through said opening, a hinged valve cover leaf mounted adjacent to and having pressure engagement with said valve, means for supplying a cleaning solvent to the valve engaging surfaces of said valve cover leaf and said valve, means for lubricating said valve and valve leaf surfaces, including a wiping device for wiping the said surface of said valve, and adjusting means for providing the desired amount of pressure engagement between said valve cover leaf and said valve.

27. In an apparatus for vacuumizing and sealing containers, the combination of a casing providing a vacuum chamber, seaming mechanism within said chamber, can conveying mechanism for introducing cans into said chamber and to said seaming mechanism and for discharging the seamed cans out of said chamber, means within said vacuum chamber for collecting any spill from the cans passing to the seaming mechanism, and an automatically operative rotary valve located outside of said chamber for discharging the said collected spill without affecting the vacuum within said chamber.

28. In an apparatus for vacuumizing and sealing containers, the combination of a casing providing a vacuum chamber, seaming mechanism within said chamber, can conveying mechanism for introducing cans into said chamber and to said seaming mechanism and for discharging the seamed cans out of said chamber, a drainage trough formed within said casing and peripherally of said vacuum chamber for collecting any

spill from the cans passing to the seaming mechanism, and an automatic rotary valve located outside of said chamber for discharging the said collected spill from said trough without affecting the vacuum within said chamber.

29. In an apparatus for sealing containers under vacuum, the combination of a casing having an opening and enclosing a vacuum chamber, seaming mechanism located in said chamber, a rotary valve having can receiving pockets and closing said opening for introducing cans and covers into said chamber, can conveying mechanism for feeding cans into a pocket of said valve, cover feeding devices for feeding covers into the same valve pocket with the can, and spacing means located in said valve pockets for holding the cans and covers in separated position to facilitate vacuumization as they enter said vacuum chamber.

30. In an apparatus for sealing containers under vacuum, the combination of a casing having an opening and enclosing a vacuum chamber, seaming mechanism located in said chamber, a rotary valve having can receiving pockets and closing said opening for introducing cans and covers into said chamber, a transfer turret located in said chamber for moving the cans and covers from said valve into said seaming mechanism, can conveying mechanism for feeding cans into a pocket of said valve, cover feeding devices for feeding covers into the same valve pocket with the can, and spacing means located in said valve pockets and in said transfer turret for holding the cans and covers in separated position to facilitate vacuumization as they enter said vacuum chamber, and pass to said seaming mechanism.

31. In an apparatus for vacuumizing and sealing containers, the combination of a casing enclosing a vacuum chamber, seaming mechanism in said chamber, means for vacuumizing said chamber, driving means for operating said seaming mechanism, and a spring-operated sylphon vacuum control bellows element disposed within said vacuum chamber and having its exterior wall in communication therewith and electrically connected with said driving means for stopping and preventing operation of said seaming mechanism by means of said spring collapsing said bellows element in the event that said vacuumizing means fails to maintain a predetermined degree of vacuum within said vacuum chamber.

32. In an apparatus for vacuumizing and sealing containers, the combination of a casing enclosing a vacuum chamber, seaming mechanism in said chamber, means for vacuumizing said chamber, driving means for operating said seaming mechanism, a spring-operated sylphon vacuum control bellows element located within said vacuum chamber and having its exterior wall in communication therewith, said bellows element being electrically connected with said driving means and collapsible by said spring for stopping and preventing operation of said seaming mechanism in the event that said vacuumizing means fails to maintain a predetermined degree of vacuum within said vacuum chamber, and means for adjusting the movement of said sylphon control to establish the desired predetermined vacuum degree.

33. In an apparatus for vacuumizing and sealing containers, the combination of a casing enclosing a vacuum chamber, seaming mechanism in said chamber, feeding devices for conveying cans and covers into said vacuum chamber and to said seaming mechanism, an electric motor

for operating said seaming mechanism and said feeding devices, a vacuum electric stop switch electrically connected in the operating circuit passing into said motor, and a spring-operated 5 sylphon vacuum control bellows element having its exterior wall disposed within said vacuum chamber for insuring proper vacuumization and sealing of said containers, said sylphon control bellows being adapted to be collapsed by said 10 spring to operate said stop switch and open said motor circuit when the vacuum condition in said chamber falls short of a predetermined degree, so that operations in said apparatus cease.

34. In an apparatus for sealing containers, the 15 combination of a seaming mechanism, can conveying devices for feeding cans into said seaming mechanism, a cover magazine for holding can covers in stacked position, feeding devices for feeding covers from said magazine to said seaming mechanism, a testing device automatically 20 operative to alternately engage against and move outwardly from the side of said stack of covers, and means operated by said testing device for stopping feeding of cans and covers when the 25 supply of stacked covers within the magazine is diminished to a position where said testing device does not engage a cover in the stack.

35. In an apparatus for sealing containers, the 30 combination of a seaming mechanism, can conveying devices for feeding cans into said seaming mechanism, a cover magazine for holding can covers in stacked position, feeding devices for feeding covers from said magazine to said seaming mechanism, an electric motor for operating 35 said seaming mechanism and said can and cover feeding devices, a low stack electric stop switch electrically connected in the operating circuit passing into said motor, and a testing device automatically operative to alternately engage 40 against and move outwardly from the side of said stack of covers to prevent exhaustion of covers within the said magazine, said testing device operating said stop switch and breaking said motor circuit when the supply of stacked covers 45 within the magazine is diminished to a position where said testing device does not engage a cover in the stack, so that operations in said apparatus cease.

36. A container handling apparatus comprising 50 a plurality of mechanisms for operating upon containers, a source of power common to said mechanisms for actuating the same, a slip clutch associated with each said mechanism and controlling delivery of power to it, an electric stop 55 device associated with each slip clutch and adapted for actuation upon the slipping of its associated clutch, and connections between said stop devices and said source of power for interrupting current delivery to said power source 60 upon actuation of any one of said stop devices, said electric stop devices being arranged in series in one circuit.

37. A container handling apparatus comprising 65 a plurality of mechanisms for operating upon containers, an electric motor for actuating said mechanisms, slip clutches located at different positions throughout the apparatus, each clutch being associated with a said mechanism, electric 70 stop devices wired in one series with said electric motor, each device being associated with a said slip clutch, and means operating when an abnormal condition actuates a said slip clutch for connecting it with its associated stop device 75 so that the motor circuit is broken at such device

and said motor and all operations of the apparatus stopped.

38. A container handling apparatus, comprising a plurality of mechanism for operating upon containers, an electric motor for actuating said mechanisms, an electric stop device associated with each said mechanism and located in different positions throughout the apparatus, each said stop device being operated by an abnormal condition in its associated mechanism to break the 10 motor circuit and stop the motor, and terminal contacts and signaling means arranged at a central location and in each of the circuits controlled by said stop devices whereby short circuit of said stop device will determine which stop device has 15 been actuated to stop the motor.

39. A container handling apparatus comprising a plurality of mechanisms for operating upon containers, an electric motor for actuating said mechanisms, electric stop devices wired in 20 series with said motor and associated with said mechanisms and located in different positions throughout the apparatus each stop device being operated by an abnormal condition in its associated mechanism to break the motor circuit and 25 stop said motor, and a terminal contact box having a plurality of contact post units wired in series with said motor and said stop devices, each stop device being wired between two adjacent contact units which permits testing of said motor circuit to ascertain which stop device is affected by the abnormal condition and to locate the affected mechanism. 30

40. A vacuum sealing apparatus for containers comprising in combination, a plurality of 35 mechanisms for operating upon containers, an electric motor for actuating said mechanisms, electric stop devices including a low vacuum control for insuring a vacuum condition in the apparatus wired in series with said motor and associated with said mechanisms and located in different positions throughout the apparatus, each stop device being operated by an abnormal condition in its associated mechanism to break the motor circuit and stop said motor, and means for 40 eliminating said low vacuum control device from said motor circuit so that the motor and through it the said mechanisms of the apparatus may be 45 operated without vacuum.

41. A vacuum sealing apparatus for containers, 50 comprising in combination a casing providing a vacuum chamber, a double seaming mechanism located within said vacuum chamber, means feeding cans into said vacuum chamber, means controlling the operation of the vacuum sealing apparatus in accordance with the degree of vacuum in said vacuum chamber, and adapted to be rendered inoperative for adjustment and repair, and means preventing feeding of cans into said vacuum chamber when said control means is inoperative. 55

42. A vacuum sealing apparatus for containers comprising in combination, a plurality of mechanisms for operating upon containers, an electric motor for actuating said mechanisms, electric stop devices including a low vacuum control for insuring a vacuum condition in the apparatus wired in series with said motor and associated with said mechanisms and located in different positions throughout the apparatus, each stop device being operated by an abnormal condition in its associated mechanism to break the motor circuit and stop said motor, means for eliminating said low vacuum control device from said motor circuit so that the motor and through it the said mecha- 70

nisms of the apparatus may be operated without vacuum, and means actuated by a container entering the apparatus for restoring said low vacuum control device in said motor circuit.

5 43. A container handling apparatus, comprising a plurality of mechanisms for operating upon containers, an electric motor for actuating said mechanisms, electric stop devices located at different positions throughout the apparatus and 10 wired in series with said electric motor, an automatic electric switch for closing the motor circuit, and means for establishing an electrical starting circuit embodying said electric stop devices, which operates said automatic switch and closes said 15 motor circuit so that the motor is operated.

44. A container handling apparatus, comprising a plurality of mechanisms for operating upon containers, an electric motor for actuating said mechanisms, electric stop devices located at different positions throughout the apparatus and 20 wired in series with said electric motor, an automatic electric switch for closing the motor circuit, means for establishing an electrical starting circuit embodying said electric stop devices, which 25 operates said automatic switch and closes said motor circuit so that the motor is operated, and means comprising a holding circuit for holding said automatic switch in circuit closing position until the motor circuit is broken by a said stop device. 30 45. In an apparatus for vacuumizing and sealing containers, the combination of a casing enclosing a vacuum chamber, seaming mechanism in said chamber, a spring-operated corrugated metallic bellows within said vacuum chamber and 35 having its exterior wall in contact with and responsive to the degree of vacuum within the

chamber, electric means operable by the collapse of said bellows by the tension of said spring to discontinue the operation of said seaming mechanism and prevent the operation of said seaming mechanism when the vacuum in said chamber 5 passes a predetermined limit.

46. In an apparatus for vacuumizing and sealing containers, the combination of a casing enclosing a vacuum chamber, seaming mechanism within the chamber, means feeding cans to be 10 seamed into said chamber and into said seaming mechanism, a spring-operated corrugated metallic bellows having its exterior wall disposed within said vacuum chamber responsive and controlled by the degree of vacuum within said chamber, and an electric control operable by the collapse of said bellows under the action of said 15 spring for interrupting the feeding action of said feeding means when the degree of vacuum within in the chamber passes a predetermined limit. 20

47. An apparatus for sealing cans under vacuum, said cans containing syrup material which is insoluble in oil, comprising in combination: a casing having an opening in its wall and enclosing a vacuum chamber in which cans and covers 25 are seamed together, a rotating valve in said opening for conveying cans into said chamber, and means for supplying measured quantities of a non-oleaginous cleaning solvent to the valve as it rotates, whereby to dissolve crystallized 30 syrup material deposited during the operation of the apparatus on the engaging surfaces of said valve as a result of handling cans containing syrup material. 35
